COIL WINDING MACHINE

Rodger J. Emmert, Dayton, Ohio, and Louis C. Goad, Muncie, and Russell W. Baker, Leo C. Shippy, John Q. Holmes, Alva W. Phelps, and Charles E. Birch, Anderson, Ind., assignors, by mesne assignments, to General Motors Corporation, Detroit, Mich., a corporation of Delaware

Application March 26, 1931, Serial No. 525,438

91 Claims. (Cl. 242—10)

This invention relates to machines for winding coils for electrical apparatus, for example, the secondary windings of an induction coil.

It is among the objects of the present invention to provide a coil winding machine of improved construction which automatically feeds to the coil winding arbor a strip of paper of predetermined length which is wound upon the arbor to provide a nonconducting cylinder which insulates the layers of turns of wire from each other.

It is a further object of the invention to provide means for reversing the operation of the machine in order to unwind wire from the coil winding arbor and to rewind the same upon the supply reels.

It is a still further object of the invention to provide means for automatically controlling the speed of the coil winding arbor whereby the angular speed will be automatically decreased as the diameter of the windings upon the arbor increases. In this way the linear winding speed is maintained substantially constant during the winding of all the layers of wire upon the arbor.

Another object of the invention is to provide means for detecting short circuits in any of the plurality of coils which are wound upon the arbor.

Another object of the invention is to provide means for automatically operating the knives which the paper insulation cylinders between the layers of wire of adjacent coils in order that the windings of wire and paper will be separated from each other at the end of the coil winding operation.

Further objects and advantages of the present invention will be apparent from the following description, reference being had to the accompanying drawings wherein a preferred embodiment of one form of the present invention is clearly shown.

40 In the drawings:

Fig. 1 is a perspective view of a machine embodying the present invention viewed from the front and one side.

Fig. 2 is a perspective view of the machine viewed from the rear and one side.

Figs. 3, 4, and 5 taken together constitute a plan view of the machine.

Fig. 6 is a side elevation looking in the direction of the arrow 6 of Fig. 1.

50 Fig. 7 is an end view looking in the direction of the arrow 7 of Fig. 4.

Fig. 7a is a sectional view on line 7a—7a of Fig. 7.

55 Figs. 8 and 9 taken together constitute a sectional view taken on line 8—8 of Fig. 6.

Fig. 10 is a fragmentary sectional view taken on the line 10—10 of Fig. 8.

Fig. 11 is a sectional view taken on the line 11—11 of Figs. 8 and 9.

Fig. 12 is a fragmentary sectional view taken on the line 12—12 of Fig. 8.

Fig. 13 is a fragmentary sectional view taken on line 13—13 of Fig. 11.

Fig. 14 is a front elevation partly in section of the paper feed roll and knife carriage taken on the line 14—14 of Fig. 4.

Fig. 15 is a sectional view on line 15—15 of Fig. 22.

Fig. 16 is a sectional view on line 16—16 of Fig. 19.

Fig. 17 is a sectional view taken on the line 17—17 of Fig. 4.

Figs. 18 and 19 are sectional views on lines 18—18 and 19—19 respectively of Fig. 20.

Figs. 20, 21, and 22 are sectional views taken respectively on the lines 20—20, 21—21, and 22—22 of Fig. 14.

Fig. 23 is a fragmentary sectional view on line 23—23 of Fig. 22 which is the same as on line 17—17 of Fig. 22 and shows a part of the mechanism in a position different from that shown in Fig. 17.

Fig. 24 is a fragmentary sectional view on the line 24—24 of Fig. 22.

Fig. 25 is a fragmentary front elevation partly in section of the paper tension bar and quick feed mechanism, the section being taken on the line 25—25 of Fig. 26.

Fig. 26 is a plan view of the paper tension bar and quick feed device.

Fig. 27, 28, 29 and 30 are fragmentary sectional views taken on the line 27—27 of Fig. 25 and show the apparatus in different positions of operation.

Figs. 31, 32, 33, and 34 are fragmentary plan views of the apparatus shown in Figs. 27, 28, 29, and 30 respectively.

Fig. 35 is a fragmentary sectional view taken on the line 35—35 of Fig. 25.

Fig. 36 is a fragmentary sectional view taken on the line 36—36 of Fig. 25.

Fig. 37 is a fragmentary side elevation of the left hand frame which supports the paper tension bar and quick feed device as viewed in Fig. 25.

Fig. 38 is a sectional view on the line 38—38 of Fig. 37.

Figs. 39 and 40 taken together constitute a fragmentary front elevation of the machine as viewed from the front of Fig. 1 showing the winding arbor, wire guide and knife operating devices.

- associated with the paper tension bar and quick feed mechanism.
- Fig. 40a is a detail side elevation of a knife blade frame.
- 5 Fig. 40b is a detail view of a knife blade frame looking in the direction of arrow 40b in Fig. 40a.
- Fig. 41 is a plan view of a commutating device viewed in the direction of the arrow 41 in Fig. 39.
- Fig. 42 is a sectional view taken on the line 10 42-42 of Fig. 41.
- Fig. 42a is a sectional view taken on the line 42a-42a of Fig. 42.
- Fig. 43 is a fragmentary perspective view looking in the direction of the arrow 43 of Fig. 5.
- 15 Fig. 44 is a fragmentary perspective view looking in the direction of the arrow 44 of Fig. 5.
- Fig. 45 is a front elevation partly in section of the winding arbor tail stop the section being taken on the line 45-45 of Fig. 46.
- 20 Fig. 46 is an end view of the tail stock looking in the direction of the arrow 46 of Fig. 45.
- Fig. 47 is a rear elevation looking in the direction of the arrow 47 of Fig. 46.
- Fig. 48 is a sectional view taken on the line 25 48-48 of Fig. 47.
- Fig. 49 is a fragmentary plan view looking in the direction of the arrow 49 of Fig. 1 showing the wire unreeling devices. The parts shown in section in Fig. 44 are taken on the line 49-49 of Fig. 50.
- Fig. 50 is a fragmentary end elevation looking in the direction of the arrow 50 of Fig. 49.
- Fig. 51 is a side elevation partly in section of the wire unreeling devices, the section being taken 30 on the line 51-51 of Fig. 49.
- Fig. 52 is a sectional view taken on the line 52-52 of Fig. 51.
- Fig. 53 is a front elevation partly in section, the section being taken on the line 53-53 of Fig. 50.
- 40 Fig. 54 is an enlarged sectional view on the line 54-54 of Fig. 53.
- Figs. 55, 56, and 57 are sectional views taken respectively on lines 55-55, 56-56 and 57-57 of Fig. 54.
- Fig. 58 is an enlarged sectional view taken on the line 58-58 of Fig. 51.
- Fig. 59 is an enlarged sectional view taken on the line 59-59 of Fig. 53.
- 55 Figs. 60 and 61 taken together constitute a fragmentary plan view of mechanism shown in Fig. 3 drawn to a larger scale. Fig. 60 shows the gear box with the cover removed.
- Fig. 60a is a sectional view on line 60a-60a of Fig. 42.
- Fig. 62 is a fragmentary sectional view on the line 62-62 of Fig. 61.
- Fig. 63 and 64 are sectional views on the lines 63-63 and 64-64 of Fig. 62.
- 60 Fig. 65 is a fragmentary sectional view taken on the line 65-65 of Figs. 61 and 70.
- Figs. 66 and 67 are sectional views taken respectively on lines 66-66 and 67-67 of Fig. 65.
- Fig. 68 is a wiring diagram of the rheostat shown in Figs. 65, 66, and 67.
- Fig. 69 is a fragmentary sectional view taken on the line 69-69 of Fig. 61.
- Fig. 70 is a sectional view on line 70-70 of Fig. 61.
- 70 Fig. 71 is a sectional view on line 71-71 of Fig. 60.
- Fig. 71a is an extension of Fig. 71.
- Fig. 72 is a side view looking in the direction of the arrow 72 of Fig. 60, a portion of a gear box 75 cover being removed.
- Fig. 73 is a sectional view on line 73-73 of Fig. 72.
- Fig. 74 is a sectional view taken principally on the line 74-74 of Fig. 71.
- Fig. 75 is a sectional view on the line 75-75 of Fig. 60.
- Fig. 76 is a sectional view on the line 76-76 of Fig. 75.
- Fig. 76a is a section taken on line 76a-76a of Fig. 76.
- Fig. 77 is a sectional view taken principally on the line 77-77 of Fig. 71.
- Fig. 77a is an extension of Fig. 77.
- Fig. 78 is a perspective view of a paper coil tube having a pig-tail attached thereto.
- Fig. 79 is a diagrammatic illustration of the operation of the short circuit detecting device.
- Fig. 80 is a diagrammatic illustration of the several mechanisms of the machine and the electric circuits and controls therefor.
- The coil winding machine comprises chiefly the following divisions or subcombination structures to which reference capital letters have been applied particularly in Figs. 1 and 2. The paper feed roll and paper knife carriage designated A 25 in Fig. 2, and the associated mechanisms for moving the carriage for turning the rolls and for operating the knife; the paper tension bar and quick feed mechanism designated by B in Fig. 1; the coil winding arbor indicated by C in Fig. 1 30 and the head stock C1 and tail stock C2 associated therewith and also the traversing wire guide C3 and the coil separating knife mechanism C4; the wire spool holders and wire unreeling devices D; the power operated mechanism 35 E including the motor E1 and mechanism in the gear box E2; and the electrical circuits for indicating a short circuit in any of the coils being wound. These divisions of the machine will be described in detail in the order mentioned.
- Paper feed roll and paper knife carriage and operating mechanism*
- Referring particularly to Figs. 2 and 17 the machine comprises a table 100 supported by leg 45 frames 101 and 102 and supporting side frames 103 and 104 providing rails 105 and 106 respectively and gibs 107 and 108 respectively for guiding for horizontal movement vertical frames 109 and 110 respectively joined by a horizontal frame 50 supporting the various parts of the paper feed roll and paper knife mechanism A. Frames 109 and 110 carry respectively bearings 113 and 114 respectively for a shaft 115 which carries a roller 116 cooperating with a roller 117 carried on a 55 shaft 118 journalled in bearing blocks 119 and 120 which are supported for vertical sliding movement by frames 109 and 110 respectively. The roller 116 is preferably metallic, the roller 117 is of soft rubber vulcanized to the shaft 118.
- These rolls are turned for purpose of sheet paper which passes between them by a manually operated wheel 121 fixed to a shaft 122 as shown in Fig. 9 which shaft is supported by bearings 123 and 124. Shaft 122 carries a gear 125 which meshes with a gear 126 fixed to a shaft 127 mounted in a bearing 128 in the frame 103 and in a bearing 129 provided by a bracket 130 fastened to the frame 103 as shown in Fig. 8.
- The shaft 127 passes through a gear housing 70 131 integral with the frame 110 as shown in Figs. 17 and 20. The housing 131 provides bearings 136 for the shaft 127. The end surfaces 136a of the bearing 136 include between them thrust bearings 137, and a gear 138 located between these 75

thrust bearings is fastened to the shaft 127 by a longitudinally splined connection provided by a key 132. The gear 133 drives a gear 134 fixed to the shaft 115. The gear housing 131 is enclosed by a cover 138.

The paper 140 which is fed by feed rolls 116 and 117 when they are turned by the hand wheel 121, is withdrawn from a paper supply roll 141 carried by a shaft 142 threadedly engaged by conical nuts 143 and 144 which threadedly support the paper feed roll 141 as best shown in Figs. 2 and 7. Nut 144 is threaded toward the left along the shaft 142 so as to clamp the paper feed roll 141 between the nuts 143 and 144, and then the nut 144 is locked in position by a lock nut 145. The shaft 142 is supported by pairs of bearings 146 and 147 carried by brackets 148 and 149 which are tied together by a cross member or frame 1498. In order to align the paper roll 141 longitudinally with respect to the paper feed mechanism there is provided a thumb screw 150 having a threaded shank 151 which screws into the bracket 149. The head of the screw 150 is provided with an annular groove 152 which receives a plate 154 having a notch 153 as shown more clearly in Fig. 6. The plate 154 is received by an annular groove 135 in the left hand end of the shaft 142. The plate 154 carries a pin 157 which holds a plain hole in the bracket 149 in order to resist rotation of the plate 154. It is apparent that by turning the thumb screw 150 the shaft 142 will be fixed longitudinally. The screw 150 is locked into position by a lock screw 156.

As shown in Fig. 22, the paper 140 passes under the roller 160, between the rollers 116 and 117 and upon a table 163 provided by the horizontal frame 111, then across an adjustable shear blade 164, then between a vertically movable shear blade 165 and a plate 166 which is fastened by screws 167 to an operating bar 168 which is connected by screws 169 to frames 170. The paper then passes over a shelf 171 and then upon an apron 172 of the shade roller type having its free end 173 joined in any suitable manner to the paper tension bar device P to be described later and shown in Figs. 27 to 30. The apron 172 is rolled upon a roller 174 pivotally supported by brackets 175 attached by screws 176 to the plate 166. The screws 176 also secure the shelf 171 to the plate 166. A spring 177 within the roller 174 tends to maintain the curtain or apron 172 taut at all times while permitting the distance between the plate 166 and the paper tension bar device to be varied.

The frames 170 are slidably guided between the frames 109 and 110 and plates 109a and 110a secured thereto in spaced relation near the top of the frame 109 and 110 by screws 180 and spacing sleeve 181 as shown in Fig. 21. The frames 170 are attached to the ends of the horizontal flange 182 of an angle bar whose vertical flange 183 is screw threadedly engaged by studs 184 locked in position by set screws 185 as shown in Fig. 22. Each stud 184 has a shank 186 of reduced diameter passing through a plane hole in the shear plate 165. The shank 186 is threaded to receive nuts 187 which confine a spring 188 which is caused to urge the shear plate 165 against a shoulder 189 provided by the threaded stud 184. By turning the stud 186 the position of the shear plate 165 relative to the shear plate 164 can be varied. Also the horizontal location of the plate 164 can be varied by first loosening the screws 164a which pass through elongated holes in the plate

164 and which are threadedly received by the table 163. An angle bar 190 having attaching lugs 191 is secured to the frames 109 by screws 192 and its horizontal leg is spaced above the table 163 providing clearance for the paper. The vertical leg of the bar 190 is abutted by but not fastened to the vertical leg of an angle bar 193 whose horizontal leg is attached to screw studs 194 which pass through plane holes in the horizontal flange of the angle bar 182. Springs 182a tend to separate the bar 193 from the bar 182 but this separation is limited by the heads of the screws 194 engaging the angle bar 182.

The mechanism for effecting downward movement of the shear blade 165 comprises links 200 pivotally attached to the cross bar 168 by screws 201 (see Fig. 22) and attached by screws 202 to levers 203 attached to shafts 204L and 204R respectively. The shaft 204L is supported by bearing brackets 205 and 206 shown in Figs. 9 and 8 respectively. The shaft 204R is supported by a front bearing bracket 207 and in the rear by a bearing 208 provided by a box 209 secured to the base 100 and provided with a cover 210. The levers 203 move with the frame 111 which provide bosses 211 between which the levers 203 are confined. The levers 203 have sliding splined connections with the shafts 204L and 204R by means of keys 212 (see Fig. 14).

The shafts 204L and 204R are operated by a pedal 215 (see Fig. 9) connected with pedal rods 213L and 213R connected respectively with levers 214L and 214R attached respectively to shafts 204L and 204R. It is apparent that when the pedal 215 is pressed downwardly clockwise and counterclockwise rotation will be imparted respectively to the shafts 204L and 204R, thereby causing levers 203L and 203R to move in the same direction in order to cause the links 200 to move downwardly. This will cause the bar 168 to move downwardly carrying with it the frames 170L and 170R which by operating through the angle bar 182 causes the angle bar 182 and studs 184 causing the shear blade 165 to move downwardly and to cooperate with the shear blade 164 to sever the paper. While the paper is being cut it is pressed against the upper surface of the blade 164 and of the table 163 by the horizontal leg of the angle bar 193 which then is being urged against the paper by the spring 182a. When the operator releases the pedal 215, a spring 216 returns the pedal to the upper position thereby reversing the action of the mechanism which will then cause the bar 168 and frames 170L and 170R, bar 182, shear blade 165 and angle bar 193 to move upwardly. This upward motion is assisted by springs 217L and 217R confined between the shear bar 164 and the angle bar 182 and received by suitable recesses 218 provided in the frames 170L and 170R.

The paper feed roll and knife device supported by frames 109, 110, and 111 is moved horizontally along the rails 105 and 106 provided by the side frames 103 and 104 respectively by chains 220L and 220R having their ends attached to the frames 109 and 110 respectively and having intermediate portions passing around sprocket wheels 221L and 221R attached to a shaft 222 and around sprocket wheels 223L and 223R fastened respectively to stub shafts 224 and 225 as best shown in Figs. 17 and 6. The shaft 224 is journaled in bearings 226 and 227 provided respectively by the brackets 205 and the side frame 104 (see Fig. 10). The shaft 225 is supported by the bearing bracket 207. The shaft 222 is the shaft which drives the chains 220L and 220R through the driving 75

sprockets 221L and 221R. This shaft 222 is turned by step-by-step motion in response to operation of the pedal 215 to effect the operation of the knife which cuts the paper.

5 The step-by-step movement of the shaft 222 is effected in response to downward movement of the pedal 215 by a mechanism which will now be described in reference to Figs. 11, 12, 13, and 8. The shaft 204R carries inside the box 209 a lever 10 230, which is attached by a screw stud 231 to the eye 232 of the rod 233 which passes downwardly through a tubular link 234 and which has a threaded portion 235 engaged by nut 236 locked in position by lock nut 237. The nut 236 has a tubular shank 238 abutting the lower end of the tubular link 234. The link 234 is pivotally attached by a rod 239 to a pair of levers 240 having hubs 241 pivotally journaled upon the shaft 222. The levers 240 support between them a rod 242 15 providing a support for a pawl 243 which cooperates with a ratchet 244 keyed to the shaft 222 by key 245. The arms 240 carry a rod 240a which fixes one end of a leaf spring 246 bearing against an arm of the pawl 233 tending to urge the end of 20 the pawl against the ratchet 244. However, when the lever 240 is in the upper position shown in Fig. 11, the pawl 243 is engaged by the lower end of a stop screw 247 threaded into a cross bar 248 integrally supported by the side walls of the box 25 30 209. Hence in the upward position of the arms 240 the pawl 243 is free of the ratchet 244. The tubular link 234 carries a lug 250 carrying a stop screw 251 the lower end of which is engageable with a stop screw 252 threaded into a block 253 and locked thereto by a lock nut 254. The block 253 is attached to the base 100 by one or more screws 255. Adjustments of the screws 252 and 251 provide means for limiting the oscillations of 35 the levers 240, thereby limiting the amount of 40 backup travel of the pawl 243. In this way the amount of clockwise rotation of the shaft 222 can be varied.

The downward movement of the pedal 215 causes the shaft 204R to turn counterclockwise 45 as viewed in Fig. 10 or clockwise as viewed in Fig. 12, thereby causing the levers 240 to move counterclockwise as viewed in Fig. 11. This causes the pawl 243 to back up from the ratchet 244 a certain amount according to the distance predetermined by the setting of the screws 251 and 252. When the operator releases the pedal 215 the return spring 216 causes the motion to be reversed, that is the lever 230 turns counterclockwise as viewed in Fig. 12 and the levers 240 clockwise as viewed in Fig. 11. Thus the spring 216 50 operates to produce the step by step motion of the shaft 222 in a clockwise direction as viewed in Fig. 11 and the consequent movement of the paper feed roll and shear mechanism from the 55 front of the machine toward the rear or upwardly as viewed in Figs. 9 and 8, or from left to right as viewed in Fig. 6.

Referring to Figs. 22, 23, 11, and 13, the horizontal frame 111 of the paper feed roll and knife 60 mechanism carries a bracket 260 attached thereto by screws 261 and providing a guide for the vertical movement of the stop bar 262 which is normally in the positions shown in Figs. 11, 13, and 22. The step by step movement of the frame toward the rear continues until the bar 262 strikes a stop screw 263 attached to a bracket 264 of channel shaped cross section straddling a rail 265 integral with the table 100. The bracket 264 70 provides a slot 266 for receiving a screw 267 threaded into the table 100. The slot provides 75

a means for adjusting the bracket 268 along the rail 265.

The paper feed roll and knife mechanism is returned to the front of the machine at a certain distance from the arbor upon which the paper 5 is wound, said distance being determined by the location of a stop screw 268 carried by a bracket 269 secured by a screw 270 to the rail 265 as shown in Figs. 11 and 9. The screw 270 passes through a slot 271 so that the bracket 269 can be adjusted 10 along the rail 265. The frame comprising members 109, 110 and 111 is returned to the forward position by mechanism operated from the front of the machine by a hand wheel 275 attached to a shaft 276 supported by a bearing 277 and another bearing which is provided by a gear housing 279 enclosed by a cover 280. Within the housing 279 the shaft 276 carries a worm 281 meshing with a worm wheel 282 loosely rotatable upon the shaft 222. When it is desired to connect the worm gear with the shaft 222 the operator moves a lever 283 pivoted at 284 upon the bracket 277, away from him or upwardly as viewed in Fig. 9, thereby causing a link 285 to move toward the rear of the machine and to cause a bell-crank lever 286 attached thereto to move counterclockwise about its pivot 287. The lever 286 has a bifurcated arm 288 each part of which carries a stud 289 received by a groove 290 in a clutch member 291. The clutch 291 is slidably splined 30 to the shaft 222 and is provided with a lug 292 engaging a notch 293 in the hub of the worm gear 282. After effecting the connection of the gear 282 with the shaft 222 by moving the lever 283 away from him, the operator rotates the shaft 276 35 by turning the hand wheel 275 thereby causing the shaft 222 to be rotated in a counterclockwise direction as viewed in Fig. 11. This causes the frame 111 to move toward the front of the machine or downwardly as viewed in Fig. 8.

During the movement of the frame 111 from a position adjacent the stop screw 263 to a position adjacent the stop screw 268 as viewed in Fig. 11, the stop bar 262 is engaged by a stop block 300 which is supported by bar 301 extending through a hole of oblong cross section in the block 300. A bar 301 is secured to the frame 100 by screws 303. Springs 304 confined between the bar 302 and screws 305 in the block 300 urge the block 300 toward the right as viewed in Fig. 11. As the operator causes the frame 111 to move toward the left in Fig. 11 by the turning of the hand wheel 275, the block 300 is engaged by the stop bar 262 and as the movement of the frame 111 continues, the block 300 is finally 50 stopped by the surface 301a of the bar 301. Then further movement of the frame 111 toward the left or toward the front of the machine is arrested. Since the operator can turn the hand wheel 275 no further in this direction, the operator is reminded of the fact the paper feed roll and knife device is in the initial position for starting the winding of a sheet of paper upon the coil winding arbor preparatory to winding wire 55 upon the arbor will be described later, but it will be understood for the present that before winding a layer on the arbor a tube of paper is wound upon the arbor of thickness to support the first layer of wire. Then, after winding the first layer 60 of wire upon this tube of paper formed by winding up that paper which is included between the arbor and the paper feed roll and knife mechanism at the time the mechanism is stopped by the engagement of the stop bar 262 with the block 70 75

300, the paper feed roll and knife mechanism must be located in a position much nearer the front of the machine preparatory to cutting off the desired length of paper to provide the insulation between the first layer of coil winding and the second layer of windings to follow after winding on the first roll of paper insulation. In order to permit further movement of the frame 111 toward the front of the machine, so that the 5 stop bar 262 can be moved against the stop screw, 268, the operator pushes the pedal 215 downwardly in order to cause the latch bar 262 to be lifted by a mechanism to be described with particular reference to Figs. 11, 15, 22, and 23. As 10 stated before, when the pedal 215 is moved downwardly it will cause the shaft 204R to turn counterclockwise as viewed in Figs. 17 and 23. This movement will cause a cam 306 to move from the position shown in Fig. 17 to that shown 15 in Fig. 23 thereby causing a lever 307 to turn clockwise from the position shown in Fig. 17 to that shown in Fig. 23. This lever 307 is pivoted upon a stub 308 carried by the bracket 260 and is provided with a notch 309 which receives a 20 pin 310 extending from the bar 262 to a slot 311 provided in the bracket 260. As soon as the lower end of the stop bar 262 is elevated above the top of the block 300, the springs 304 which were then compressed beyond their normal state 25 of compression are permitted to expand to move the block 300 toward the right and under the stop bar 263. Therefore, when the operator releases the pedal 215 to permit the spring 216 to restore the mechanism to normal condition in 30 which the cam 306 occupies the position shown in Fig. 17, the stop 262 will remain upon the top surface of the block 300. The stop 262 is urged downwardly against the block 300 by a spring 312 attached at one end to a post 313 fixed 35 to the frame 111 and the other end to a post 314 fixed to the frame 111 and the other end to a post 314 fixed to the lever 307. Now when the operator continues to turn the hand wheel 215 in such a direction as to cause the frame 111 to move toward the front of the machine as viewed in Fig. 40 11, the stop bar 262 will ride along the top of the block 300 and then down its inclined surface and then drop into normal position. The operator continues to turn the hand wheel 215 until the stop bar 262 engages the screw 268, whereupon 45 further movement of the hand wheel in this direction is arrested. This lets the operator know that the feed roll and knife mechanism is in the desired position for preparing the sheet of insulation paper to be wound upon the arbor after 50 the first layer of turns have been wound thereupon.

During the intermittent step by step motion of the feed roll and knife mechanism from the front of the machine to the rear the stop bar 262 will engage the beveled surface of 300a of the block 300, thereby causing the bar 262 to be lifted upwardly so that its lower end will ride along the top surface of the block 300 and finally drop off into the position shown in Fig. 11 as the 55 frame moves toward the end of the machine.

Paper tension bar and gripper device

The mechanism which operates to quickly feed to the winding arbor a strip of paper of predetermined measured length severed from the supply roll and which operates to smooth out the wrinkles upon the paper as it rolls on the arbor will be described as in Figs. 25 to 37 inclusive. The frames 103 and 104 carry hard metal wear 70 pieces 323 and 324 providing guides for the hori-

zontal sliding movement of a lower gripper bar 320 carrying rods 321 which support for vertical sliding movement an upper gripper bar 322. The rods 321 are threaded at their upper end to receive nuts 325 which confine springs 326 which 5 urge the bar 322 toward the bar 320. The approach of the bar 322 toward the bar 320 is limited by stop screws 327 threaded through the bar 322 and locked in position by lock nuts 328. The bars 320 and 322 are caused to move horizontally by a mechanism operated by the pedal 215. This mechanism comprises a link 330 attached to the pedal and to a lever arm 331 integral with a tubular shaft 332 which is loosely rotatable upon a shaft 333 journaled in bearings 15 334 provided by the frames 103 and 104. The shaft 332 has integral arms 335 carrying pins 336 connected by links 337 with pins 338 which pass through lugs 338a integral with the bar 320. The pins 338 also pass through blocks 340 which 20 are slidable in horizontal guides 341 provided by the frames 103 and 104. Plates 342 attached to the frames 103 and 104 confine springs 343 bearing against the blocks 340 and urging these blocks toward cover plates 344. Thus the springs 25 343 urge the bars 320 and 322 into the position shown in Figs. 27, 26, 31, 34, and 30.

Referring to Figs. 30 and 34, in which the circle 400 represents the arbor upon which the paper and wire is being wound, it will be noted 30 that the paper 140 has been fed into such position that it is fed between the arbor 400 and the wire represented by line 346. In such position of the paper its free edge will be thrown by the wire 346 moving toward the arbor 400 with such 35 force against the arbor that it will be wound up with the wire upon the arbor. The bars 320 and 322 are spaced apart such a distance shown in Fig. 30 that the wrinkles in the paper will be substantially ironed out while the paper is being drawn over a ridge bar 350 and under a companion groove 351 provided respectively by the bars 320 and 322. The paper gripper bars are locked in the position shown in Figs. 30 and 34 by latch bars 352, one at each end of the bar 322 and cooperating with a locking plunger 353, 40 carrying a latch plate 354, which provides a notch 355 which receives the latch bar 352 when in the position shown in Figs. 30 and 34. At the end of the operation of winding the measured strip of paper upon the arbor and during the 45 winding of a layer of coil thereon, the operator prepares the next strip of paper to be wound upon the arbor at the end of the winding of said wire turns. Before the operator can manipulate the paper feed roll and knife mechanism he grasps the knob 360 shown in Fig. 35 to cause a rod 361 to move against the action of a spring 362 toward the left thereby causing a lever 364 attached to a shaft 365 to move clockwise as viewed in Fig. 35. Referring to Figs. 30 and 27, clockwise movement of the shaft 333 will cause similar movements of cams 366 from the position shown in Fig. 30 to that shown in Fig. 27, the cams 366 lift levers 367 pivoted upon pins 368 thereby causing rods 369 engaged by these levers to move upwardly and the heads 369a of these rods to engage under surfaces of bar 322 to cause the same to move upwardly from the position shown in Fig. 30 to that shown in Fig. 28. When this occurs the stop bar 352 shown in Figs. 31 to 34 50 inclusive, will be located above the latch plate 354, so that thereafter the bar 322 will be held in the upward position against the compression of the springs 326 due to the fact that the stop bars 55

70 75 pieces 323 and 324 providing guides for the hori-

352 rest upon the latch plate 354 which has been urged under the stop bars by the spring 370, surrounding the shanks 371 of the plungers 353. The plungers 353 are guided by brackets 372 attached to the plates 373 which are attached to the frames 103 and 104. These brackets provide guides for the plungers 353 and their shanks 371 and for the springs 370 which bear against the brackets 372 and the shoulders 353a of the plungers 353. Thus it is apparent that the springs 370 operate to urge the latch plates 354 toward the stop bars 352. Thus when these bars are elevated above the latch plates 354 these latch plates will be snapped by the springs 370 under the stop bars 352. Therefore, after the operator releases the operating knob 360, the gripper and tension bar 322 will remain in the upper position shown in Fig. 27 while the spring 362 operates to return the shaft 365 and cams 366 to normal position as shown in Fig. 30.

While the machine is operating to wind a layer of wire on the paper previously fed to the arbor, the operator next turns the hand wheel in the direction to feed paper from the supply roll 141 through the paper feed roll and knife mechanism along the apron 172 until the edge of the paper appears toward the front or toward the left of the gripper tension bar 320 and 322 as shown in Fig. 27. The front edge of the paper will of course not touch the wire 346 then being wound upon the arbor 400. The operator then presses the pedal 215 downwardly to effect the severing of the sheet of paper then upon the apron 272 from the remainder on the supply roll. The downward movement of the pedal 215 causes the tension bars 320 and 322 to move while remaining in separated positions from the positions shown in Fig. 27 to those shown in Fig. 28 and a little further into the position shown in Fig. 29. During the movement of the bars from the positions shown in Fig. 27 to those shown in Fig. 28 these bars remain separated due to the fact that the stop bars 252 extending from the bar 232 ride along the upper surfaces of the latch plates 354. But as the bars 320 and 322 move still further horizontally toward the right from the positions in Fig. 28 to those shown in Fig. 29, the stop bars 252 move away from the right hand end of the latch plates 354 thereby permitting the springs 326 to move the bar 322 downwardly into the position shown in Fig. 29. In this position the bar 322 grips the paper 140 against the bar 350 carried by the lower tension bar 320. The bars 320 and 322 are held in this position against the compression of springs 343 due to the fact that a latch plate 375 carried by the bar 320 is engaged by latch lever 376 rotatable with a shaft 377 and urged in a counterclockwise direction by means to be described later, the shaft 377 is journaled in the bearing provided by the frame 104. Thus by one operation of the pedal, the paper is cut off and the paper gripper and tension bars are located in a position preparatory to feeding the paper quickly against the wire being wound upon the arbor. As stated before, the paper tension and gripper bars are latched in retracted position shown in Fig. 29 by the latch 376 which at the proper instant is automatically released by a mechanism to be described later. It will be sufficient for the present to state that the latch lever 376 is automatically moved from its position shown in Fig. 9 thereby permitting the spring 343 to be quickly released and to quickly move the plate 320 and 322 from the position shown in Fig. 29 to that

shown in Fig. 30 thereby carrying the front edge of the paper 140 against the downwardly moving wires 346 then being wound upon the arbor. By the manipulation of the knob 360 shown in Fig. 35 to elevate the gripper bar 322, by the turning 5 of the hand wheel 121 to feed paper from the supply roll to the gripper bars and by the pressing of the pedal 215 to cut off the paper, and to locate the gripper bars in gripping relation and in position retracted from the arbor, during the 10 winding of a layer of wire coils the operator has prepared a sheet of paper of predetermined length and has conditioned the machine for the automatic feeding of the paper to the arbor at the proper instant without stopping the winding 15 of wire.

Winding arbor

A winding arbor C of Fig. 1 is supported by a head stock C1 and a tail stock C2 in this figure. 20 The arbor C comprises a rod 400 having a longitudinal groove 401 and provided adjacent its left hand end with a central bore 402 which receives a spring 403 and a plunger 404 as shown in Fig. 77a. Plunger 404 pushes against the 25 shank 405 of a center 406 and tends to retain a pin 407 carried by the shank 405 in a bayonet slot 408. A collar 409 pressed fitted in the bore 402 retains the plunger 404 and spring 403. Center 406 has a conical head received by a similar conical recess in a shaft 410. The shaft 410 is drivingly connected by a screw 411 with a collar 412 having a pair of diametrically opposite notches 413 for receiving the ends of a pin 414 extending through the center 406. This 30 construction is also shown in Fig. 75. The members 410, 411, 412 comprise the head stock C1 of Fig. 1.

The tail stock C2 of Fig. 1 will now be described with particular reference to Figs. 45 to 48. The 40 tail stock comprises a frame 420 which provides the bearing 423 for the hand wheel shaft 122 used to manually feed paper to the apron 172. The frame 420 supports and guides for horizontal movement a sleeve 421 carrying antifriction bearings 422 and 423 for a tail stock spindle 424. 45 The spindle 424 is provided with a conical recess 425 for receiving the conical end 426 of the arbor rod 400. The spindle supports a protecting sleeve 427 urged by a spring 428 toward the left until pins 429 carried by the sleeve, engage a shoulder 430 provided by the spindle 424. Rotation of the sleeve 421 is prevented by a rack 431 attached thereto and received by longitudinal grooves 432 provided by the frame 420. The 50 rack 431 meshes with a gear 433 supported by a shaft 434 having a bearing in the frame 420 and a bearing in a bushing 435 received by a lateral bore 436 provided by the frame 420. This bushing is attached to the frame by screws 437. The 55 shaft 434 carries a lever 438 which may move between two adjustable stop screws 439 and 440 threadedly received by lugs 441 and 442 respectively carried by the bushing 435. These stop screws control the limits of movements of the tail stock spindle 424. The spindle is yieldingly maintained in either of its positions corresponding to location of the lever 438 against the stop screw 439 or the stop screw 440 by a coil spring 450 having one end attached to a hook 451 connected to the frame 420 and the other end to a post 452 attached to a lever 453 attached to a shaft 434. When the lever 438 is located as shown in Fig. 45 against stop screw 439, the spring 450 is positioned so that its center line of 60 65 70 75 80 85 90 95 98 99

action will be located on the right hand side of the vertical center line passing through the shaft 434 as viewed in Fig. 47. In Fig. 47 the spring 450 tends to rotate the shaft 434 clockwise or counterclockwise as viewed in Fig. 45. When the lever 438 is turned clockwise as viewed in Fig. 45 in order to move it against the stop screw 440, the shaft 434 will be rotated counterclockwise as viewed in Fig. 47 so that the spring 450 will be located to bring its center line of action on the left of the vertical center line passing through the axis of shaft 434. In this way the spring will be effective to urge the shaft 434 counterclockwise as viewed in Fig. 47 or clockwise as viewed in Fig. 45.

When the tail stock spindle 424 has been retracted from the head stock spindle 410, the arbor C can be removed. The retraction of the tail stock spindle draws the conical recess 425 away from the tapered end 426 of the spindle rod 400 permitting the rod to be supported only by the sleeve 427. This sleeve is retracted by grasping the flange 427a thereof and moving the same toward the right against the compression of the spring 428.

Referring to Figs. 77a and 78, before the arbor rod 400 is mounted upon the head stock and tail stock, a plurality of paper coil tubes 460 are placed thereon. Each coil tube 460 is attached by a wire staple 461 to a pigtail 462 having a relatively long portion 462a and a short portion 462b extending from the staple 461. Each coil tube 460 has a notch 463 in longitudinal alignment with the staple 461. The coil tubes are passed staple end foremost over the right hand end of the arbor and are moved toward the left hand end. Just before passing the tubes 460 over the arbor rod 400 the pigtail end 462a is tucked into the inside of the tube 460 and the tube is so located with respect to the rod 400 that the groove 401 of the rod 400 will receive the pigtail end 462a, which serves then as a means for drivingly connecting the arbor rod 400 with the coil tube 460. The free end of a wire 346 to be wound upon the arbor is stripped of its insulation and is wound around the pigtail end 462b prior to winding wire upon the tube 460. In this way the pigtail end 462a serves as a terminal for the inside end of the coil. While the coil is on the coil winding arbor of the winding machine, the pigtail end 462a provides a ground connection between the coil being wound and the arbor. This ground connection is included in an electrical circuit to be described later, which operates for the purpose of protecting a short circuit in the coil while it is being wound. If the coil is used as a secondary coil of an ignition coil or similar induction apparatus, an iron core of small iron wires may be placed within the coil tube 460. In such case the pigtail end 462a serves as a means for grounding the coil upon the iron core within the core tube.

Wire unreeling and reeling apparatus

Referring to Figs. 49 and 59, the frames 103 and 104 support respectively triangular frames 473 and 474 respectively carrying a table 470, which as shown in Figs. 1, 2, 50, and 51 is located in an inclined position. The table 470 supports a plurality of wire spool holders and unreeling and reeling devices D associated therewith, there being as many devices and holders as there are coils to be wound upon the arbor C. As the devices D are similar, but one of them will be described with particular reference to Figs. 51 and 53.

The table 470 supports a bearing bushing 475, carrying anti-friction bearings 476 and 477 supporting a spindle 478; spacer sleeves 479, gear 480 and spacer sleeve 481 which are retained by a nut 482 threaded upon the lower end of the spindle 478. The spindle 478 extends through an opening 483 in a bottom cover plate 484 attached to the lower side of the frame 470. The spindle 478 and nut 482 extend through a packing gland comprising a disc 485 attached to the cover 484 and cooperating with a threaded bushing 486 to enclose a packing 487. Thus, the space within the hollow table 470 which is closed by the cover 484, packing gland discs 485 and bushings 475 can be used as a chamber for enclosing grease or other lubricant for lubricating the bearings of the spindles and the gears which drive them. The gear 480 is driven by a gear 490 mounted on a shaft 491 supported by brackets 492 attached to the table 470 as shown in Fig. 53. Referring to Fig. 49, there are two shafts 491 supported by anti-friction bearings 492 and 493 carried by the table 470. The left hand ends of the shafts 491 extend into a gear housing 494 provided by the table 470 and are fastened to gears 495 meshing with an intermediate gear 496. Referring to Fig. 53 the gear 496 is fastened to a shaft 497 supported by antifriction bearings 498 and 499 carried respectively by the frame 470 and a gear housing cover 500. The gear 501 meshes with the gear 502 fastened to a shaft 503 journaled in antifriction bearings 504 and 505 supported respectively by the table 470 and the gear housing 500. The shaft 503 is attached to a sprocket wheel 506 driven in a manner to be described later by chain 507 also operated by hand crank 508 whose hub 509 is carried by the shaft 503. The hub 509 carries a pin 510 received by a transverse notch 511 of the shaft 503.

The spindle 478 supports an unreeling arm rod 520 having bearings in the spindle at 521 and 522. The rod 520 is frictionally connected with the spindle 478 by means including felt discs 523 and 524 located respectively between the upper end of the spindle 478 and a shoulder 525 of the spindle rod 520 and between the lower end of the spindle 478 and the flange of a sleeve 526, which is urged upwardly by spring 527 retained by nuts 528 threadedly engaging the threaded lower end 529 of the rod 520. By adjusting the nuts 528 the compression of the spring 527 can be varied in order to vary the frictional pressure exerted against the felt discs 523 and 524, which serve to frictionally connect the spindle 478 with the unreeling arm rod 520. The packing gland disc 485 is threadedly connected with a tubular cover 530 which encloses the spring 527 and nuts 528 and protects them against damage or change in adjustment.

The unreeling arm 531 is constructed of light weight rigid material and is attached to the tubular hub 532 of a spring cup 533. The cup 533 is attached to the outer end of a spiral clock spring 534, the inner end of which is received by notches 535 in a sleeve 536, which provides a bearing for the hub 532 which is journaled upon the part 537 of the rod 520. The sleeve 536 is provided with a hole 538 for receiving a pin 539, the inner end of which is received by any one of four notches 540, provided by the unreeling arm rod 520. The pin 539 is riveted to the interior of a resilient split ring 541 which may be placed around the sleeve 536 in order to locate the pin 539 so that it will provide a driving connection between the rod 520 and the sleeve 536. The

split ring 541 is retained by a sleeve 542 which may be elevated from the position shown in Fig. 54 in order to remove the split ring 541. The spring cup 533 receives a spring cup cover 543, 5 which encloses the spring 534. The sleeve 536 is secured to the part 537 of the rod 520 by a screw 546. The unreeling arm 531 carries at its free end a bearing bushing 547 supporting a grooved pulley or a wire guide 548.

10 Before the spool 550 can be placed upon the table surrounding the spindle 478 shown in Fig. 51, the unreeling arm and spring cup 532 are removed from the unreeling arm rod 520. This is quickly accomplished by lifting the sleeve 542 15 above the upper end of the resilient split sleeve 541, then the sleeve 541 may be withdrawn carrying with it the pin 539 which connects the sleeve 536 with the rod 520. After the screw 546 is removed, the entire assembly parts 531, 532, 20 and 536 can be removed from the rod 520, in order to allow the operator to place the spool 550 upon the table and surround the spindle 478.

The spool 550 is generally made of copper and the inside made of wire is grounded thereto.

25 Since the ground connection between the wire and the spool is in the electrical circuit employed for detecting a short circuit in any coil wound upon the arbor, it is necessary to insulate the spool from the table. This is accomplished by an insulating disc 548 (see Fig. 51) upon which the spool rests and an insulating tube 549 surrounding the spindle 478 and extending through the spool. Referring to Fig. 49 the spool 550 is prevented from turning by having its lower flange 30 engaged by three pointed plungers 551 which are guided for sliding movement by nonconducting blocks 552 secured to the table 470 by screws 553. Each block houses a spring 554 which urges the plunger 551 toward the spool flange. One of these 35 plungers provides an electrical contact with the spool and is included in the circuit which is employed for detecting a short circuit in any coil wound upon the arbor.

The spool having been placed upon the table 45 as shown in Fig. 51 and the unreeling arm 531 having been mounted upon the rod 520 in the manner shown, the wire 346 to be unreeled from the spool is passed around the pulley 548 and then upwardly and around a pulley 560 and then 50 downwardly and around traversing wire guide pulleys 561 and 562 and then to the arbor C as shown in Figs. 6 and 39. The pulley 560 is pivoted upon a screw 570 attached to an arm 571 carries a pin 577 which engages a leaf spring 55 573. The bracket 573 is attached by nut 574 to a stud or post 575, the lower end of which is attached by nut 576 to the table 470. The arm 571 carries a pin 577 which engages a leaf spring conductor 578 capable of engaging a conductor 60 579. The conductors 578 and 579 are attached to the arm 573 and are insulated from each other by nonconducting washer 580 and nonconducting sleeve 581 through which passes the screw 582 cooperating with a nut 583 for securing these parts to the arm 573. The nut 583 is insulated from the arm 573 by washer 584. The conductor 579 is an electrical contact with the screw 582. The conductor 578 bears against a metal washer 585 which connects this conductor 70 with the arm 573 which serves as a ground connection through the frame 513 and post 575. The conductors 578 and 579 are in an electrical circuit for automatically stopping the operation of the machine when the wire breaks. The electrical system for effecting this will be described later.

For present purposes it will be sufficient to state that while the wire 346 is being unreeled, there is sufficient tension therein to pull the pulley 560 downwardly and thereby cause the pin 577 to engage the contact 578 and to separate it from the contact 579. As long as contact 578 is separated from contact 579 the machine will continue to run unless stopped in some other manner. However, when the wire 346 breaks, pulley 560 will be relieved of the tension of the wire and 10 the contact 578 will move of its own resiliency upwardly into engagement with the contact 579. During the unreeling of wire from the spools 550 the unreeling arms 531 and the unreeling rods 520 rotate coaxially with the axis of the spindles 15 478 but the spindles 478 remain stationary. The springs 527 which operate through the felt washers 523 to frictionally connect the unreeling arm rods 520 with the spindles 478, provide sufficient resistance to the rotation of the rod 520 20 so that the wires 346 are maintained taut. Since the unreeling arms 531 are connected with the rods 520 through resilient connections provided by the spiral springs 534 any tendency to jerk the wire due to sudden starting of the coil winding arbor will be materially relieved.

If the operator desires to unwind wire from the arbor and to rewind it upon the spools 550, the shaft 503 is turned by the hand crank 508 (see Figs. 50 and 53) or by power applied through the chain 507 and sprocket 506. When the shaft 503 is power operated, the arbor C is also power operated in the unwinding direction, so that as the arbor rotates to unwind the wire the unreeling arms 531 will be rotated in the direction reverse to that which takes place during the unreeling operation, power being transmitted from the shaft 503 to the unreeling arms through the gearing connecting the shaft 503 with the shafts 491 and thence from the shafts 491 to each of 40 the spindles 478 and then from spindles 478 through the frictional connections with the rods 520 provided by the felt washers 523 and 524. This feature of the machine can be advantageously used sometimes when a short circuit of 45 a coil has been detected. Rather than continue the winding of all the coils when one of them appears to be short circuited, the operator can unwind the wire of all the coils from the arbor and rewind this wire on the spools. This rewinding upon the spools can continue until the short circuit has been detected. In case the short circuit has been caused by a wire from which the insulating varnish has been rubbed off crossing over another wire adjacent thereto, these defects 50 can be remedied very quickly by placing a bit of oiled silk under the bared portion of the wire which caused the short circuit. Then the winding of wire upon the arbor can continue. Thus, 55 it appears that the machine provides for automatically inspecting the coils for short circuit during the winding thereof so that at any time a short circuit exists the operator can stop the machine and rewind the wire sufficiently to find out the cause of the short circuit and to remedy it. 60

Power driving mechanism

Referring to Fig. 2, the power driving mechanism including the motor E1 and gearing and controls within the gear box E2 will now be described. The motor E1 rests upon a base 600 attached to the table 100 and drives a shaft 601 having a bearing 602 in a bracket 603 supported by the table 100 and a bearing 604 carried by the end wall 605 of the gear box E2 as can be 70 75

seen in Fig. 70. Shaft 601 carries a gear 606 meshing with a gear 607 journalled on a rod or stub shaft 608 supported by a gear housing 609 and the wall 605. The gear 607 meshes with 5 the gear 610 having a bearing 611 journalled on a shaft 612 journalled in a bearing 613 provided by a gear box 614 and in a bearing 615 provided by the end wall 616 of the gear box E2. The shaft 612 passes through a stuffing box 10 comprising a nonadjustable bushing 617, packing 618 and a threaded bushing 619 (see Fig. 71), which can be screwed into a wall of the gear box 614. The shaft 612 is axially movable and is held in the position shown in Figs. 70 and 71 by 15 a spring 620 which bears at its right hand end against a tubular member 621 secured to the shaft by pins 622 and having clutch teeth 623. The spring 620 bears at its left hand end against thrust washers 624 bearing against the bearing 611. Compression of the spring 620 is transmitted through the bearing 611 to the inside or cam member 625 of a one-way roller clutch. The hub 626 of the clutch cam 625 bears against a washer 627, the washer 627 against a spacing 20 sleeve 628, the spacing sleeve 628 against a washer 629, and the washer 629 against the end of the boss 630 which carries the bearing 613. The clutch 623 is engageable with clutch teeth 633 of the hub 634 of the gear 610. The hub 634 of 25 gear 610 has other clutch teeth 635 meshing with clutch teeth 636 of a clutch shell 631, which together with the clutch cam 625 cooperates with rollers 638 to provide a one-way driving connection between the shell 631 and the clutch cam 30 625. The cam 625 is connected through its hub 626 with a bevel gear 640, meshing with a bevel gear 641 pinned to a shaft 642 journalled in a bearing 643 provided by the gear box 614 and in a bearing 644 provided by the frame 104 35 as more clearly shown in Fig. 65. The shaft 642 is pinned to a sprocket wheel 645 which receives the chain 507 which passes around the sprocket 506 as shown in Fig. 53. The chain 507 passes over idle or guiding sprocket wheels 446 and 647. The gear box 614 is enclosed by cover 648 attached by screws 649 to the box 614 and by screws 650 to the gear housing 609.

The one-way clutch provided by the members 631, 638 and 625 is so constructed that, during normal rotation of the shaft 601 to effect rotation of the winding arbor shaft 400 in the direction to wind wire thereon, no motion will be imparted from the shell 631 to the cam 625. But if the driving motor E1 is reversed for the 55 purpose of unwinding wire from the arbor, then motion will be transmitted through the clutch or members 631, 638 and 625 to effect rotation of the spindles 478 of the wire reeling and unreeeling devices D for the purpose of rewinding wire 60 on the spools 550 as the wire is being unwound from the arbor shaft 400 as explained before.

When it is desired to turn the spindles 478 in the direction for winding wire on the spools 550, but not to turn any other part of the machine, the operator uses the hand crank 508. When the hand crank turns, the chain 507 and hence the bevel gears 641 and 640 will be turned, but the one-way clutch provided by the members 631, 638 and 625 will permit of moving 70 these parts without rotating the shell 631 and any of the gearing connected therewith.

When it is desired to manually operate the machine in a reverse direction, the operator pushes on a hand wheel 651 fixed to the front 75 end of the shaft 617 in order to move the shaft

toward the rear or toward the left as viewed in Figs. 70 and 71. This motion will engage the clutch 623 with the clutch 633, the handle being the hand wheel 651 being turned to facilitate this engagement. The shaft 612 is held in this 5 position against the compression of the spring 620 by a latch bolt 652, which is yieldingly urged upwardly by spring 653 (see Figs. 71 and 71a). The bolt 652 is guided by bearing 654 provided in the tubular extension 655 in the gear box end 10 wall 616. This extension 655 carries a bearing 656 for a shaft 657, carrying a crank and an eccentric cam 659 which is adapted to bear against a shoulder 660 on a latch bolt 652. When the eccentric 659 is in the position shown in Fig. 71a, 15 the latch bolt will be held down against the compression of the spring 653. When it is desired to operate the machine manually by turning the hand wheel 651, the operator turns the crank 658 up so that the eccentric 659 will be 20 moved to release the bolt 652, then when the operator pushes the shaft 612 toward the machine or toward the left as viewed in Fig. 70 and 71, the bolt 652 will be permitted to move upwardly against the shaft 612 and have its upper 25 end located between the bearing 615 and a collar 661 attached to the shaft 612. The latch bolt 652 having moved into this position, the operator is not required to hold the shaft 612 from moving toward him against the compression of 30 the spring 620. The operator may then turn the hand wheel 651 and operate the entire machine manually through the connections provided by the clutch 623, 633. As stated before, this hand-wheel 651 is used to turn the machine back- 35 wards when it is desired to operate the machine backwards slowly rather than at a more rapid rate by power transmitted by the motor. After having used the wheel 651 the machine is 40 conditioned for normal operation by turning the crank 651 down to retract the bolt 652 from its position between the collar 661 and the bearing 615. This will permit the spring 620 to return the shaft 612 to normal position disconnecting the clutch 623 from the clutch 633. 45

Referring to Fig. 71, the shaft 601 extends within the gear box E2 and there carries a bevel gear 670 which meshes with a bevel gear 671 pinned to the shaft 410 which carries the winding arbor head stock collar 412. The shaft 410 is 50 journalled in antifriction bearings 672 and 673 mounted respectively upon the side walls 674 and 675 of the gear box E2 as shown in Fig. 75. The gear box E2 cooperates with a cover 676 to provide a housing 677 for change speed gearing for 55 connecting the arbor shaft 410 with two oppositely rotating feed screw shafts 678 and 679 which are journalled in suitable antifriction bearings provided also by the gear box side walls 674 and 675, one of these bearings being shown at 60 679a in Fig. 60a. The shafts 678 and 679 are connected with meshing gears 680 and 681 respectively. The shaft 679 extends into the gear housing 677 and is therein connected with gears 682 and 683. The gear 682 is adapted to mesh 65 with a gear 684 mounted together with a connecting gear 685 upon a stub shaft 686. The gear 685 meshes at all times with a gear 687 fastened to the arbor shaft 410. The gear 683 is meshable with a gear 688 meshing with a gear 70 689 also fastened to the arbor driving shaft 410. The gear 688 rotates upon a stub shaft 690. The stub shaft 686 has a shank which passes through plates 691 and 692 and has a threaded end receiving a nut 693 as best shown in Fig. 73. A 75

spacer 694 surrounds the shank of the stub shaft 686. When the nut 693 is tightened, the parts 691, 692, and 694 will be tightened against the shoulder 695 of the shaft 686. In this way the 5 plates 691 and 692 are secured together in spaced relation. The other three corners of the plates 691 and 692 are clamped together in spaced relation in a similar manner by the bolt which acts as the stub shaft 690 and other bolts 696 and 697. 10 For example, the bolt 690 receives a nut 690a and extends through a spacer bearing 690b. When the nut 690 is tightened the plates 691 and 692 and the spacer 690b will be clamped in correct spaced relation with respect to the bolt 690. The 15 plate 691 and securing bolts 686, 690, 696, and 697 provide a frame which as shown in Fig. 77, is oscillatable about the shaft 410. The gear housing cover 676 provides a stuffing box bearing 700 for a stub shaft 701 connected outside the box 20 with a lever 702. The shaft 701 is coaxial with the shaft 410 and has a central socket 703 for receiving a reduced end portion 704 of the shaft 410. The plate 691 is journalled on the shaft 410 and the plate 692 upon the shaft 701 so that 25 when the lever 702 is turned, the frame carrying the change speed gears can be moved in order to disconnect one train of gearing and connect another in order that the ratio of speed of the shaft 410 relative to the feed screw shafts 678 and 30 679 be varied. In order to hold the lever 702 in either of its positions of adjustment, the gear case cover 676 is provided with holes 710 and 711 each adapted to receive the end of a plunger 712 guided by a tubular boss 713 in the end of 35 the lever 702 said boss housing a spring 714 which is confined between an end wall of the boss and a shoulder 715 on the plunger 712. The spring 714 operates to urge the plunger 712 into either of the holes 710 or 711. The plunger 712 is provided with a handle 716 for the purpose of withdrawing the plunger from either of the holes 710 or 711. When a relatively coarse feed of the 40 wire guiding wheels 561 and 562 is desired, the lever 702 is located so that its plunger 712 is received by the holes 710 as shown in Fig. 73. This will bring the gear 683 into mesh with the gear 688 and thus connect the arbor shaft 410 with the screw shaft 679 through gears 689, 688, and 683. When a relatively fine feeding of the wire 45 guiding wheels 561 and 562 is desired, the plunger 712 is retracted and the lever 702 moved downwardly into a position which will align the plunger 712 with the holes 711 and the knob 716 can be released to lock the lever 702 in this position. 50 This movement of the lever 702 brings the gear frame so that the gear 683 will be demeshed from the gear 688 and the gear 682 meshed with the gear 684. In this way the arbor shaft 410 is connected with the feed screw shaft 679 through 55 the gears 687, 685, 684 and 682. 60 The feed screw shafts 678 and 679 are provided with buttress feed screws 678a and 679a adapted respectively to feed toward the right and toward the left as viewed in Fig. 60, as indicated by arrows 678b and 679b respectively. The screws 678a and 679a cooperate respectively with nuts 718 and 719 guided by a recess 720 in a swinging frame 721 which is pinned to a rod 722 slidable horizontally through suitable bearings provided by the side walls 674 and 675 of the gear box E2. The nuts 718 and 719 are yieldingly urged apart by springs 723. Stop pins 724 received by notches 725 in these nuts limit the separation of the nuts 70 by the springs 723. The springs 723 serve to

transmit pressure yieldingly from the frame 721 through the nuts to the screw shafts.

The frame 721 provides a notch 726 for receiving a block 727 carrying a stud 728 connected with a lever 729 pivoted upon a stud 730 supported by a cross bar 731 attached by screws 732 to the gear box walls 674 and 675. The lever 729 is pivotally connected by stud 733 with a block 734 which fits into aligned notches 735 provided by two blocks 736 and 737 attached by screws 738 to a sliding bar 739 as best shown in Fig. 71. The bar 739 is guided by notches 740 and 741 provided respectively by the side walls 674 and 675. The bar 739 is attached to a rod 742 carrying a plurality of brackets 743 each of which carries a pair of wire guiding rollers 561, 562 (see Figs. 1 and 39). The rod 742 is horizontally and axially slidable in bearings provided by brackets 744 and 745 (see Figs. 39 and 40). Referring to Fig. 76, the motion of the slide bar 739 is yieldingly arrested by pairs of spring pressed plungers 750 and 751 guided by the walls 674 and 675 respectively, said walls providing sockets for springs 752 and 753 respectively retained by screw plugs 754 and 755 respectively. 25

By a mechanism now to be described, the nut 718 is automatically released from the screw 678a after a predetermined travel of the nut toward the right and the swinging frame 721 is caused to swing diagonally toward the screw 679a instead of in a plane perpendicular to the axis of rotation of this screw. After a predetermined travel of the nut 719 along the screw 679a toward the left, the nut 719 is automatically retracted from the screw 679a and the swinging frame is caused to move diagonally toward the screws 678a to engage the nut 718 again with the screw 678a, whereupon said screw moves nut 718 toward the right. This cycle of operation is repeated as long as the machine is in operation. Referring to Figs. 71 and 77, the swinging frame 721 carries a hard metal wear piece 760, opposite sides thereof being engaged by levers 761 and 762, which are urged by springs 763 and 764 against said part 760. The piece 760 has an extension 765 which is urged by said lever against a lug 766 integral with the plate 767 attached by screws 768 to the bottom wall 769 of the gear box E2. Referring to Fig. 77 it will be noted that the extension 765 of the piece 760 bears against one side 766a of the lug 766, while the nut 718 is in engagement with the screw 678a. As the nut 718 travels toward the right, the extension 765 of the wear piece 760 will move toward the right along the surface 766a of the lug 766. When the piece 760 arrives at the position 760a in Fig. 77, the extension 765 will be clear of the lug 766 so that the spring 763 will cause the lever 761 to move said piece 760 downwardly from the position 760a to the position 760b. As this part moves downwardly, it is caused to move diagonally by reason of the fact that the extension 765 of the piece 760 is caused to move between diagonal surfaces 766c of the lug 766 and a diagonal surface 770 of a lug 771 also integral with the plate 767. In this way the nut 718 is automatically disconnected from the screws 678a and the frame 721 is caused to swing in a diagonal direction to move the nut 719 slightly toward the left while moving it into engagement with the screws 679. The purpose of this diagonal movement is to impart to the wire guiding bar 739 and rod 742 a relatively coarse feed so that as the wire begins to traverse in a direction from right toward left, it will be coarsely fed at that instant when the paper is being wrapped with the wire 75

upon the arbor. The nut 719 being in engagement with the screws 679a, is fed toward the left by said screw, thereby causing the swinging frame extension or wear piece 760 to move toward the left from the position 760b to 760c shown in Fig. 77. During the movement of the piece 760 in this direction its extension 765 is urged by the lever 762 against the surface 766b of the lug 766. When the piece 760 has arrived at the position 760c, its extension 765 is clear of the lug surface 766b whereupon the lever 762 will cause the piece 760 to move in a diagonal direction after the position shown in cross section in full lines in Fig. 77. This diagonal movement takes place by reason of the fact that the wear piece extension 765 is caused to move between a surface 766d on the left hand end of the lug 760 and a surface 780 of a lug 781 also integral with the plate 768. Thus, the swinging frame 721 is automatically caused to swing in a clockwise direction as viewed in Fig. 71 in order to retract the nut 719 from the screw 679a and to move the nut 718 against the screw 678a. During this swinging movement, the swinging frame is caused to move slightly toward the right in order to impart to the feed bar 739 and feed rod 742 a relatively coarse feed so that the wire then being wound upon the arbor will have a relatively coarse pitch at the time paper is being wound with the wire upon the arbor. The feature of momentarily increasing the pitch or lead of the wire at the instant of reversal of the travel of the wire guides and at the instant that the paper is fed to the arbor to be wound thereon, is an advantage because it has been found that the liability of short circuit is considerably minimized if the closely spaced turns at the start of one layer of windings are not exactly superposed upon the preceding layer of coil windings. In other words, the layers are staggered so that alternate layers are superposed longitudinally relative to the axis of the coil whereas adjacent layers are shifted so that the margin of one layer extends beyond the margins of layers immediately preceding and succeeding.

45 Coil paper separating knives and control

The side wall 675 of the gear box E2 and the tail stock frame 420 provide bearings for a knife shaft 800 carrying a plurality of equidistant clamp brackets 801 (see Figs. 74, 46, 40 and 40a). Each bracket is clamped around the shaft 800 by screw 802, the bracket 801 carries a pivot pin 803 providing means for pivotally supporting a knife blade frame comprising members 804 and 805 which straddle the bracket 801 and which are secured together by screw 806 and a nut 807 and which hold a blade 808 of thin steel such as a bit of safety razor blade. The blade 808 and its supporting frame 804, 805 can be removed without removing the clamp bracket 801 from the shaft 800. This is accomplished by withdrawing a pin 809 which is received by an annular groove 810 by the pivot pin 803. The retainer pin 809 is riveted to one end of a relief spring 811 fixed to the clamp bracket 801 by a screw 812. Motion is imparted from the bracket 801 to the blade holder 804, 805 through a compression spring 813. The brackets 801 are located on the shaft 800 in a manner such that the blades 808 will cut the paper insulation wrapped upon the coil winding arbor C between the coils of wire wound thereon. The shaft 800 is rocked automatically to cause the blades 808 to engage each new wrapping of paper wound upon the arbor by a mechanism operating in response to movement of the wire guide

shifter bar 739. Referring to Figs. 76, 76a and 71 the blocks 737 carry a pair of spring pressed plungers 815 urged downwardly by springs 816 retained by a cover 817 which is attached to the block 737. These plungers have triangular heads 818, each engageable with a triangular button 819 mounted on a lever 820 fastened to a shaft 821 which is supported by the side walls 674 and 675 of the housing E2. The shaft 821 carries a lever 822 carrying a roller 823 engageable with a lever 824 fixed to a knife shaft 800 and urged clockwise as viewed in Fig. 71 by lever 824. A spring 825 surrounding pins 826 and 827 attached respectively to the lever 822 and to a block 828 secured by screws 829 to the side walls 675 urges the lever 822 clockwise as viewed in Fig. 71. When neither of the plungers 815 engage the button 819 of the lever 820 the spring 825 is effective to move the levers 822 and 824 toward the left as viewed in Fig. 71, thereby rotating the shaft 800 counterclockwise to retract the knife blades 808 carried by the clamp brackets 801 from the winding arbor C. When either of the plungers 815 engage the button 819, the lever 822 is moved counterclockwise to permit the spring 824a to move the lever 824 clockwise in order to move the knife blades 808 against the paper wound upon the arbor C. One cycle of operation of the knife operating mechanism takes place for each swing of the wire guide bar 739; therefore, each paper wrapping is cut following the wrapping thereof and before the next wrapping is wound upon the arbor.

Automatic control of the paper gripping and tension bars.

Like the block 737 shown in Fig. 76, the block 736 carries a pair of plungers 830 urged downwardly by springs 831 retained by a cover 832 fastened to the block 736. Each plunger 830 has a head 833 (see Fig. 76a) adapted to engage a button 834 attached to a lever arm 835 pivoted upon a stud 836 carried by a bracket 837 fastened to the back wall 605 of the gear housing E2 as shown in Figs. 75 and 71. The lever 835 is integral with a lever 838 connected by a link 839 with a lever 840 which is fixed to the shaft 333 which carries the cams 366 which operate the levers 367 shown in Figs. 27 to 30 and 36, which elevate the rods 369 which elevate the tension bar 322. One of the plungers 818 engages the button 834 during each stroke of the shifter bar 739 and causes the levers 835 and 838 to move clockwise as viewed in Fig. 75, and the lever 840 to move counterclockwise as viewed in Fig. 71, and the shaft 333 to move clockwise as viewed in Figs. 27 to 30. These operations take place following the completion of the winding of a strip of paper upon the arbor. Thus, the machine automatically provides for moving the upper tension bar 322 from the position shown in Figs. 30 and 34 to the position shown in Figs. 27 and 31. In other words the machine performs automatically that which the operator can perform by pulling out the knob 360 shown in Fig. 35. Then all the operator has to do is to turn the handle 321 to feed the paper along the apron 372 and then press the pedal to retract the paper tension bars from the arbor C and set these bars in gripping position as shown in Fig. 29 in which position the bars are retained against the compression of springs 343 by the latch lever 376 which engages the plate 375 attached to the bar 320 as shown in Fig. 29.

The clockwise movement of the lever 376 to 75

release the tension bars for the purpose of shooting the paper against the wires being wound upon the arbor will now be described with particular reference to Figs. 60 to 65, 69, and 70. The block 5 736 is engageable at the end of its strokes with set screws 850 and 851 carried respectively by lever arms 852 and 853 respectively, which as shown in Fig. 69, are pivoted upon pins 854 and 855 respectively carried by brackets 856 and 857 10 respectively secured by screws 858a and 859a respectively to the back wall 605 of the frame E2. The levers 852 and 853 are integral with arms 858 and 859 carrying respectively ball headed screws 860 and 861 cooperating with ball sockets 862 and 863 provided respectively by links 864 and 865 having ball sockets 866 and 867 respectively cooperating with ball headed screws 868 and 869 which are threadedly secured to a lever 870 (see Fig. 70) fastened to a shaft 871 15 having bearings 872 and 873 provided by the brackets 856 and 857. The lever 870 is connected by a spring 874 with the wall 605, which as shown in Fig. 70, urges the shaft 871 in a counterclockwise direction and the levers 852 and 853 toward 20 each other and a lever 875 integral with lever 852 and a stop screw 876 carried thereby against a stop button 877 carried by the housing wall 605.

Referring to Figs. 62, 63, and 64, the shaft 30 871 is fixed to a lever 880 having a bifurcated notched end 881 receiving a pin 882 fixed to a link 883 having its ends connected by pins 884 and 885 respectively with members 886 and 887 which are respectively pivotally mounted upon shafts 377 and 889. The shaft 377 which carries the latch 376 is fixed to a plate 890 carrying a spring post 891 attached by a spring 892 to a spring post screw 893. The spring 892 urges the plate 890 against the 35 stop stud 894 and hence urges the latch 376 downwardly into a position retaining the latch plate 375 as shown in Fig. 29. As shown in Fig. 62, the shaft 377 pivotally supports a ratchet plate 895 which is angularly adjustable relative to the 40 plate 890 and can be fixed thereto in the desired positions of adjustment by the bolt 896 which passes through a plane hole in the plate 890 and through a slot 897 in the plate 895 and which receives a nut 898. The lever 886 supports a 45 pawl 899 upon the pin 884 the point of the pawl being received by a notch 900 in the plate 895. The pawl 899 has an arm 901 attached by spring 902 to a spring post screw 903 fastened to a bracket 904 which is fastened to the side frame 50 104.

Whenever one of the stop screws 850 or 851 in Fig. 60 is moved by the block 736 carried by the wire guide shifter bar 739, clockwise rotation will be imparted to the shaft 871 thereby causing the link 883 to move toward the left in Fig. 62 and the lever 886 to move counterclockwise whereby the pawl 899 will move into the notch 900 of the plate 895 and cause the same to move counterclockwise and to impart through the bolt 896 55 and plate 890, counterclockwise movement of the shaft 377 and pawl 376. As viewed in Fig. 29 this movement is clockwise and therefore a movement which causes the latch lever 376 to 60 release the plate 375 to permit the springs 343 to move the paper tension bars from the position shown in Fig. 29 to that shown in Fig. 30 in order to shoot the paper quickly against the wires being wound upon the arbor. This mechanism is so timed with respect to other operations 65

of the machine that the paper will be shot against the wires at the time the wire guide rod 742 reaches the limits of its travel in either direction.

Control of speed of the winding arbor

In order that the linear winding speed of the wire will be substantially constant as the diameter of the coil increases, the machine provides automatic means for decreasing the angular speed of the winding arbor. This is accomplished by automatically decreasing the speed of the motor in response to movement of the wire guide shifting bar 739. Referring to Fig. 68, the driving motor E is represented diagrammatically as 15 having a field coil 910 in circuit with a rheostat comprising a plurality of resistance elements 911 connected with segments 912 which are insulated from each other and are located in a circular row. A ring 913 is connected by wire 914 with one 20 terminal of the field 910 and with one of the segments 912e to designate the end segment of the rheostat, the starting segment being 912f which is connected by wire 915 with one of the motor brushes 916, and with the rheostat resistances 911. The ring 913 and the circular row of segments 912 is engaged by brush 917. When the brush 917 contacts with segment 912e, all of the resistance elements 911 are short circuited thereby preventing the motor to run at full speed. 30 By a step-by-step motion, the brush 917 is caused to move about the axis of the rheostat in a counterclockwise direction adding each time an increment of resistance following the winding of each layer of coil turns upon the arbor. By providing as many segments 912 as there are wrappings upon the arbor or layers of wire upon the arbor, the winding of the coil will be completed by the time the brush 917 has arrived at the segment 912f. It should be noted that there is 40 no segment between 912e and 912f. Therefore following the winding of the coil, the machine will automatically move the brush 917 into a position in which it contacts only with the ring 913 and is located between the segments 912f 45 and 912e. In this position of the brush the field circuit is broken and the motor will stop automatically after the completion of the coil.

Referring to Figs. 61, 65, 66, and 67, the ring 913 and the circular row of segments 912 are 50 supported by a nonconducting base 920 attached by screws 921 to the bracket 904. The bracket 904 supports a stub shaft 889 shown also in Fig. 62, supports a ratchet 922 to which is attached an indicating dial 923 carrying a series of equally spaced members cooperating with an index mark 924 on the base 920 as shown in Fig. 61. The ratchet 922 carries a nonconducting block 925 providing a socket 926 for the brush 917 which is urged by spring 927 into engagement with the ring 913 and the segment 912. The ratchet 922 has teeth engaged by a pawl 930 pivoted upon a pin 931 carried by the lever 886 and having an arm 932 connected by a spring 933 with a screw 934 attached to the lever 886. Backing up of the ratchet 922 is prevented by a pawl 935 pivoted upon a stud 936 attached to the bracket 904 and having an arm 937 connected by spring 938 with a screw 939 attached to the bracket 904. 65

As stated before, during each swing of the wire guide shifting bar 937 there will be a clockwise movement of the shaft 871 as viewed in Fig. 62. This will be accompanied by a movement of the link 883 to the left and consequently a clockwise 70

movement of the lever 866, pawl 930, ratchet 922 and brush 917.

Detection of short circuits in the coils

5 Referring to the wiring diagram shown in Fig. 79, and to Fig. 49, one of the metal points 551 which engages a metal spool 550 is connected by wire 940 with a commutator segment 941. These segments are arranged in a circular row and are 10 insulated from each other and there are as many segments as there are spools 550. As stated before, the inner end of the wire 346 ground on the spool 550 is grounded on the spool and the outer end which is attached to the arbor C is grounded 15 on the arbor. The row of segments 941 is engaged by a brush 942 rotating about the axis of the commutator and engageable with a ring 943 which is connected by wire 944 with a current source such as a battery 945 connected with 20 ground by wire 946. A voltmeter 947 is connected across the line wires 944 and 946. As the brush 942 rotates, it moves successively into and out of engagement with the segments 941 which may be numbered corresponding to numbers applied to the spools. Spool 550 #1 is of course connected with segment 941 #1, spool 550 #2 with segment 941 #2. The wire from spool 550 #1 is used to wind coil #1, and the wire from spool 550 #2 is used to wind coil #2 etc. The machine 25 is started with full spools hence the voltmeter will read the same as the brush 942 makes a complete revolution provided there are no short circuits of the coil. If the coil is short circuited, this short circuit will be indicated by a drop in 30 voltage at the time the commutator segment connected with that coil is engaged by the brush 942. The voltmeter 947 is located in the front of the machine as shown in Fig. 1. When a drop in voltage is indicated, the operator stops the machine and reverses it to unwind the wire so that the short circuit may be found. If the brush 942 is in contact with segment 941 #2 when the voltmeter indicates a short circuit, the operator will 35 inspect coil #2 as the wire is unwound therefrom.

Referring to Figs. 39, 41, 42, 42a, and 60a, the shaft 678 carries a gear 950 driving a gear 951 fixed to a shaft 952 having bearings 953 and 954 in a bracket 955 attached by screws 956 to the 40 wall 675 of the housing E2. The shaft 952 carries an extension 952a supporting sleeves 957 and 958 which clamp between them a nonconducting arm 959 which carries the brush 942. The sleeve 957 is driven by the shaft 952 through a lug 960. The sleeve 958 is driven by the sleeve 957 through a set screw 961 which provides means for securing the sleeve 958 to the sleeve 957 in the desired 45 position of angular adjustment. The sleeve 958 is connected to the arm 959 through a lug 962. The sleeves are retained by nut 963 secured to the threaded extension 952a of the shaft 952. The segment 941 and the ring 943 are embedded in a nonconducting base 964 attached by screws 965 to the bracket 955. These screws secure rings 966 clamping between them a pyrolin disc 967 which provides a transparent cover for the base 964, through which cover the operator can observe the location of the brush arm 959 which 50 serves as an index in cooperation with a series of numbers, one to seven, marked upon the upper surface of the upper disc 966. These numbers indicate the circuit being made by the commutator brush 942, for example, if the arm 959 is adjacent numeral 1 on the ring 966, and the

voltmeter indicates a short circuit, the operator will then know that coil #1 is defective.

Electrical control of machine

Referring to the wiring diagram in Fig. 80, and 5 to Fig. 1 it will be noted that the machine is controlled by three manually operated switch buttons carried by the control block 970 attached to the table 120. The block 970 carries a forward control button 971, a stop control button 972, and 10 a reverse control button 973. The button 971 operates a normally open switch having contacts 974 and 975. The button 972 operates a normally closed switch having contacts 976 and 977. The button 973 operates a normally open switch hav- 15 ing contacts 978 and 979.

The buttons 971, 972 and 973 control an electromagnetic controller for causing the motor to operate in either direction or to stop. The controller has electro-magnet windings 980 and 981 20 which when energized separately will attract to the left an armature 982 or to the right an armature 983 respectively. The armatures 982 and 983 are connected by a rod 984 carrying a pin 985 received by an eye in the end of a lever 987 25 which is maintained in a central position by springs 988 and 989. The lever 987 insulatingly supports contacts 990, 991, 992, and 993. The contact 990 is adapted to engage a pair of contacts 994, 995 when the lever 987 swings to the 30 left or to engage a pair of contacts 996, 997 when the lever swings to the right. The contact 991 is in engagement with an arcuate contact 998 and engages a contact 999 when the lever 987 swings toward the left or with the contact 1000 35 when the lever 987 moves toward the right. The contact 992 is in engagement with an arcuate contact 1001 and engages a contact 1002 when the lever 987 moves counterclockwise and with the contact 1003 when the lever 987 moves clockwise. 40 The contact 993 engages contact 1004 and 1005 as the lever 987 begins counterclockwise movement and then the contacts 1006 and 1004 as the lever completes its counterclockwise movement. The contact 993 engages first contacts 45 1007 and 1008 as it begins clockwise movement and finally contacts 1009 and 1008 at the end of its clockwise movement. The contacts 1005 and 1006 are connected by resistance 1010. The contacts 1007, 1009 are connected by a resistance 50 1011. The contacts 1006, 1009 are connected together by a wire 1012 with the field winding 910 of the motor E. The contacts 1004, 1008 are connected together and by a wire 1013 with the positive line wire 1014. The negative line wire 55 1015 is connected by line wire 1016 with contact 1001. The positive line wire 1014 is connected by wire 1017 with contact 998. Contacts 999 and 1002 are connected together by wire 1018 and by wire 1019 with motor brush 916. Contacts 60 1000 and 1003 are connected together by wire 1020 and by wire 1021 with brush 918. As explained with reference to Fig. 68 the motor field 910 is connected with rheostat arm 917 and the rheostat resistor 911 is connected by wire 1022 65 with negative line 1015.

Wire 1023 connects contact 995 with magnet coil 980 and with switch contact 974. Wire 1024 connects contact 994 with switch contact 975. Wire 1025 connects wire 1024 with wire 1026 connecting with wire 1017. Wire 1025 also connects with wire 1027 which connects contact 996 with contacts 979. Wire 1028 connects contact 997 with magnet coil 981 and with contact 978. Contact 977a is connected by wire 1030 with 70 75

relay armature 1031 normally pulled by a spring 1032 against a contact 1033 connected by wire 1034 with wire 1022. The magnet coil 1035 of the relay switch is connected with wire 1026 and by wire 1036 with contact 919 located adjacent the negative terminal 911a of the rheostat resistor 911. The wire 1036 is connected by wire 1037 with contact 578 of the wire tension controlled switch shown in Fig. 51. The other contact 579 of this switch is connected by wire 1038 with wire 1034 of the negative line wire 1015.

Résumé of mode of operation

The manner of using the machine will be described starting with the arbor C removed from the machine as indicated by Figs. 43 and 44. The operator places upon the rod 400 of the arbor C a plurality of coil tubes or cores 460 shown in Fig. 78, and also 39 and 40. These coil tubes are placed upon the rod 400 in the manner indicated in Fig. 77a. It will be noted that the longer end 462a of the pig tail connection is located inside the coil tube 460 and is received by the longitudinal groove 401 of the rod 400. In placing the coil tubes 460 upon the rod 400 the pig tail end 462a is pushed into that end of the tube 460 which has the notch 463. Hence as the pig tail end 462 is pushed inside the tube 460, this pig tail end is received by the notch 463. The pushing of the pig tail end 462a inside the tube 460 is incidental to placing the tubes upon the arbor rod 400. In placing the tubes upon the rod 400, the conical end 426 of the rod is threaded into the tubes 35 and at the same time this conical end 426 pushes the pig tail end 462a into the tube in the manner shown in Fig. 77a. The tubes are so located with respect to the rod 400 as the latter is threaded into the tubes, that the pig tail end 462a will be received by the longitudinal groove 401 of the tube. Thus the groove 401 provides a recess for receiving the pig tail ends 462a so that the tubes 460 will remain cylindrical while on the arbor rod 400. The pig tail end 462a of each tube cooperates with the side walls of the groove 401 in the manner of a key providing a driving connection between the driving rod 400 and the coil tube 460. After the arbor rod 400 has been substantially filled with coil tubes 460, the arbor C is placed in position on the end stock C1 and the tail stock C2 as shown in Figs. 39 and 40. To each shorter pig tail end 462b there is attached the bared end of a wire 346 extending from a wire supply spool and passing over the wire guiding wheels 561 and 562 when in the initial or start position shown 561' and 562' respectively, as shown in Figs. 39 and 40. The machine is now ready for winding the first layer of wire and paper upon the coil tubes 460 located upon the arbor rod 400.

While winding the first layer of turns upon the coil tubes 460 there is also wound upon the tubes a layer of paper having considerably more turns than layers of paper which insulate subsequent layers of wire from each other. This first sheet of paper is prepared for winding upon the arbor in the following manner. The clutch operating lever 283 shown in Fig. 1, is moved so as to connect the shaft 276 with the shaft 222 shown in Fig. 8. Then the operator turns the hand wheel 275 shown in Figs. 1 and 10, in a direction such as to cause the paper feed roll and knife carriage 140 to move toward the front of the machine until the stop plunger 262 strikes the stop block 300 shown in Figs. 11 and 8. When this occurs the

motion of the hand wheel 275 is arrested. Then the operator knows that the paper feed roll and knife carriage is located at the correct position for cutting off a sheet of paper at the desired distance from the arbor C. Then the operator turns the hand wheel 121 in order to feed from the paper supply roll 141 a sheet of paper into the position shown in Fig. 27. Then the operator presses the pedal 215 in order to cut off the sheet of paper from the remainder of the paper connected with the paper supply roll and in order to move the paper tension and quick feed bars 320 and 322 into the position shown in Fig. 29, in which position these bars are latched by the latch lever 376. The pressing of the lever 215 also causes the stop plunger 262 to be elevated so that the stop block 300 which has been pressed to the left of the position shown in Fig. 11, when the paper feed roll and knife carriage was being advanced toward the front of the machine by the turning of hand wheel 275, will be released so that the springs 304 will push the block 300 to the right and under the stop plunger 262 while the latter was lifted due to the downward movement of the pedal 215. In this way the paper feed roll carriage is automatically released from the intermediate stop block 300 by the act of cutting off the first strip of paper to be wound upon the arbor. The machine is now ready for the power winding of wire and paper. The operator presses the forward control button 971, which effects the closing of circuits shown in Fig. 80 for the purpose of causing the motor to turn the arbor C in a forward or counterclockwise direction as viewed in Fig. 30. As soon as the arbor starts to turn, a mechanism is set into operation for lifting the latch lever 376 so that while winding wire 346 upon the coil tubes 460 the paper tension and quick feed bars 320 and 322 will be spring operated from the position shown in Fig. 29 to that shown in Fig. 30 thereby causing the front edge of the paper 140 to move against the wires 346 whereupon the moving wires will drag the paper against the coil tubes 460 and cause the paper to be wound thereon while winding a layer of coil turns. During the rotation of the arbor to wind wire and paper thereon the wire guide wheels 561 and 562 are caused to move laterally from left to right during the first movement of the guide rod 742 in that direction. While the paper is being wound upon the arbor it is being pulled between the ridge bar 350 of the lower tension bar 320 and the surface defining the groove 351 in the upper tension bar 322 as shown in Fig. 30. The pulling of the paper over the ridge bar 350 while being wound tends to eliminate wrinkles from the paper so that it will be wound in a smooth cylindrical manner upon the paper tubes.

While completing the winding of the first layer of coil turns, the operator prepares for the winding of a second sheet of paper upon the arbor, said second sheet to be wound immediately upon the winding of the first coil turns. The stop plunger 262 having been released from the intermediate stop block described, the operator will turn the hand wheel 275 in a direction to move the paper feed roll and knife carriage toward the front of the machine until the stop plunger 262 engages the front stop screw 268, whereupon the turning of the hand wheel 275 will be arrested. This indicates to the operator that the paper feed roll and knife carriage is in the farthest forward position to cut off the shortest strip of paper required for providing the insulation between the first and second layers of coil turns.

The paper feed roll and knife carriage having been brought into this most forward position, the operator moves the lever 283 into a position to disconnect the shaft 276 from the shaft 222. The 5 hand wheel 275 is no longer to be manipulated until after the completion of winding a series of coils upon the arbor. From this time on the feeding of the paper feed roll and knife carriage from the front toward the rear by equal increments is 10 performed automatically.

The operator then turns the hand wheel 121 in order to feed paper so that its front edge will be brought into the position shown in Fig. 27. Then as before, the operator presses the pedal 215 in 15 order to cut off a sheet of paper from the supply roll and in order to locate the paper tension and quick feed bars 320 and 322 in the position shown in Fig. 29. At the completion of the swing of the wire guide bar 742 toward the right, the guide 20 bar feeding mechanism is reversed so that the guide wheels will begin to move toward the left for the purpose of guiding the wire for winding the second layer of coil turns upon the arbor. Just as the wire guide bar 742 begins to move to 25 ward the left, the latch 376 is lifted to permit the paper to be moved from the position shown in Fig. 29 to that shown in Fig. 30, whereupon the front edge of the paper will be gripped between the arbor and the wire 346 being wound thereon, 30 and the second strip of paper will be wound upon the arbor.

The operations of turning the hand wheel 121 to bring the edge of the paper 140 into the position shown in Fig. 27 and the pressing of the 35 pedal 215 to sever the paper and to prepare the machine for the quick movement of the severed sheet against the wires being wound upon the arbor are performed each time by the operator while a layer of wire is being wound. Each time 40 the operator presses the pedal 215 the pawl 243 is backed up with respect to the ratchet 244 shown in Fig. 11. When the operator releases the pedal 215 the spring 216 returns the pedal and at the same time causes the pawl lever 240 to rotate 45 clockwise about the shaft 222 while the pawl 242 engages the ratchet 244 to move the latter clockwise. Thus each time the pedal is released the paper feed roll and knife carriage are moved a short distance toward the rear of the machine in 50 order to increase the distance between the carriage and the arbor. In this way the strips of paper which are successively wound upon the arbor are gradually increased in length so that the same number of turns of paper will be wound 55 between successive layers of wire although the diameter of those turns is gradually increasing.

As previously explained with reference to Figs. 68 and 80, the speed of the motor E1 is gradually decreased so that the linear winding speed 60 of the wire will remain constant. The automatic decreasing of the speed of the motor by slight increments is effected through the use of an automatically operated rheostat having a resistor 311 and a wiper 917 shown in Fig. 80. When the 65 desired number of layers of wire have been wound, the wiper 917 will have arrived at a position in engagement with contact 919 whereupon the machine will be automatically stopped. At the end of the winding operation of layers of closely spaced coils of wire the machine may be operated if desired to wind on an additional layer of less closely spaced turns. The rheostat wiper 917 can be manually reversed a slight distance 70 from the stopping position so as to permit operation of the machine for winding on the last turn 75

of wire. Before winding on the last layer of wire and paper the change speed gears shown in Fig. 60 are connected by manipulating the handle 702 for the purpose of effecting a relatively coarse feeding of the wire guide bar 742. Following 5 the winding of coarsely spaced turns the machine is stopped and the end of the wire is attached to the coil by adhesive tape. During the winding of each layer of wire, the severing knives 808 are 10 automatically operated for the purpose of dividing or separating each paper strip coiled about the arbor in order that at the end of the coil winding operation each coil tube 462 will be 15 separated from the other and will not be connected with its neighbor by the paper insulation wrapping. In other words, at the end of the coil winding operation the arbor C will support a plurality of separate coils, each comprising layers of turns of wire separated by tubes of paper insulation. By manipulating the lever 438, the tail stock arbor 20 424 is separated from the conical end 426 of the arbor rod 400, thus permitting the arbor C to be removed from the machine so that the several coils may be removed therefrom.

In case of breakage of wire leading from any 25 spool to any coil being wound upon the arbor, the machine will be automatically stopped because the stopping of the motor is effected by the closing of switch contacts 578 and 579 as has been described with respect to Fig. 80. The broken 30 wire can be repaired by baring the ends of their insulation, twisting them together, and then placing a bit of oiled silk between the twisted portion and the other portions of wire wound upon the arbor. The wire having been repaired, the tension of the wire retains the switch 578, 579 in open 35 position so that the machine can be started again in the forward direction by pressing the forward button 970.

A short circuit in any coil is detected by a low- 40 er voltage reading of the voltmeter 941. The sudden swing of the voltmeter needle toward the left as viewed in Fig. 1, will be made more pronounced by placing a resistance 944a in the wire 45 944. As previously explained, the coil having the short circuit can be determined by the location of the commutator arm 959 relative to the dial 966 shown in Fig. 41, at the time the voltmeter needle swings toward the left. When this short 50 occurs the operator will press the stop button 972 to cause the machine to stop. The operator will 55 then turn the handle 658 up and push in on the hand wheel 651. While the handle 658 is up, a latch is permitted to lock the hand wheel shaft 612 in such position that the hand wheel 651 will be connected with the gear 610, through the coupling members 623 and 633 shown in Fig. 70. By 60 turning the hand wheel 651 the direction of rotation of the arbor can be reversed so as to unwind the wire therefrom and at the same time the unreeling arms 531 will be rotated through power manually applied through the hand wheel 651 in a direction to cause wire to be rewound upon the spools 550. During the rotation of the arbor to 65 unwind wire therefrom, the wire guide bar 742 will be caused to move in the reverse direction. On arriving at the end of its stroke in the reverse direction, the swing of the bar 742 cannot automatically begin in the other direction due to the fact that the bar feeding mechanism is not automatically reversible. The bar feeding mechanism is manually conditioned for feeding of the bar in another direction while the arbor is being 70 75 rotated, by the manipulation of the shaft 722 to which the swinging nut members 718 and 75

718 are attached as shown in Fig. 71. As has been explained, in connection with the automatic feeding of the wire guide bar 742 during the winding of wire upon the arbor, the shifting of the feed nuts 718 and 719 with respect to the feed screws 678 and 679 is effected automatically through the agency of springs 763 and 764 as shown in Fig. 77. Since it is inherent in the mechanism that these springs will resist a reverse 5 swinging operation of the swinging frame 721, shown in Fig. 71, it is necessary that this frame be manually swung if it is desired to unwind more than one layer of wire from the arbor. In order to accomplish this the swinging frame shaft 722 is 10 provided with an arm 1100 having a tapped hole 1101 for receiving a handle 1102 which may be screwed into position when needed as shown in Fig. 1. This handle 1102 is manipulated to swing the frame carrying the feednuts while turning the 15 hand wheel 661 to reverse the motion of the arbor or while the motor reversely rotates the arbor in order to rewind the wire upon the spools 550. The handle 1102 can be, of course, manipulated to 20 control the swinging of the feed nut frame 721 during the reversal of the arbor and the rewinding of wire upon the spools under power applied by the motor which can be reversed by pressing the reverse button 973.

While the form of embodiment of the present 30 invention as herein disclosed, constitutes a preferred form, it is to be understood that other forms might be adopted, all coming within the scope of the claims which follow.

What is claimed is as follows:

35 1. A coil winding machine comprising, in combination, a winding arbor; a wire supply spool holder; oscillating means for guiding wire from the supply spool in layers upon the arbor; an electric motor for operating the machine; a source of electric power; a movable bar carrying conductive 40 contact bridges which are insulated from each other; a solenoid including a movable core for maintaining the bar in an operating position; a spring urging the bar from operating position into normal position; a plurality of stationary contacts which when bridged by the contacts of the bar connect the source of electric power with the field of the motor, the armature of the motor and the solenoid; a manually operable switch for connecting the source of electrical power with the solenoid whereby the bar moves against the tension of the spring into operating position in which its contacts bridge said stationary contacts whereby the bar is maintained in such position 45 by the solenoid and the motor caused to run; and means for interrupting the connection between the electrical power source and the solenoid.

50 2. A coil winding machine comprising, in combination, a winding arbor; a wire supply spool holder; oscillating means for guiding wire from the supply spool in layers upon the arbor; an electric motor for operating the machine; a source of electric power; a movable bar carrying conductive 55 contact bridges which are insulated from each other; a solenoid including a movable core for maintaining the bar in an operating position; a spring urging the bar from operating position into normal position; a plurality of stationary contacts which when bridged by the contacts of the bar connect the source of electric power with the field of the motor, the armature of the motor and the solenoid; manually operable means for effecting the movement of the bar from normal 60 position into operating position in which its contacts bridge said stationary contacts whereby

the bar is maintained in such position by the solenoid and the motor caused to run; and means for interrupting the connection between the electric power source and the solenoid.

3. A coil winding machine comprising, in combination, a winding arbor, a wire supply spool holder; oscillating means for guiding wire from the supply spool in layers upon the arbor; an electric motor for operating the machine; a source of electric power; a movable bar carrying conductive contact bridges which are insulated from each other; a solenoid including a movable core for maintaining the bar in an operating position; a spring urging the bar from operating position into normal position; a plurality of stationary contacts which when bridged by the contacts of the bar connect the source of electric power with the field of the motor, the armature of the motor and the solenoid; a manually operable switch for connecting the source of electrical power with the solenoid whereby the bar moves against the tension of the spring into operating position in which its contacts bridge said stationary contacts whereby the bar is maintained in such position by the solenoid and the motor caused to run; a rheostat connected in series with the field of the motor, said rheostat including a contact movable in response to movement of the wire guiding means for gradually increasing the field strength of the motor to decrease its speed as the coil diameter increases, and means for interrupting the connection between the electrical power source and the solenoid.

4. A coil winding machine comprising, in combination, a winding arbor; a wire supply spool holder; oscillating means for guiding wire from the supply spool in layers upon the arbor; an electric motor for operating the machine; a source of electric power; a movable bar carrying conductive contact bridges which are insulated from each other; a solenoid including a movable core for maintaining the bar in an operating position; a spring urging the bar from operating position into normal position; a plurality of contacts which when bridged by the contacts of the bar connect the source of electric power with the field of the motor the armature of the motor and the solenoid; a manually operable switch for connecting the source of electric power with the solenoid whereby the bar moves against the tension of the spring into operating position in which its contacts bridge said stationary contacts whereby the bar is maintained in such position by the solenoid and the motor caused to run; a normally yieldingly closed solenoid control switch connected in series with said solenoid; a switch connected in series with said solenoid; a switch connected in series with the field of the motor, said switch including a stationary arcuate contact and another contact engaging and intermittently moving over said arcuate contact in response to the movement of the wireguiding means, a motor stop auxiliary circuit connecting one side of the electric power source with a stationary contact adjacent the arcuate contact and including an electro-magnet adjacent the solenoid control switch for opening the same, said stationary contacts being connected with the field of the motor by said movable contact when the latter moves during an intermittent motion out of engagement with said arcuate contact, whereby the electro-magnet is energized and the solenoid control switch opened so that the bar follows the tension of the spring whereupon the motor stops; and manu- 55 60 65 70 75

- ally operable means for rendering the solenoid ineffective.
5. A coil winding machine comprising, in combination, a winding arbor, a wire supply spool holder; oscillating means for guiding wire from the supply spool in layers upon the arbor; an electric motor for operating the machine; a source of electric power; a movable bar carrying conductive contact bridges which are insulated from each other; a solenoid including a movable core for maintaining the bar in an operating position; a spring urging the bar from operating position into normal position; a plurality of stationary contacts which when bridged by the contacts of the bar connect the source of electric power with the field of the motor, the armature of the motor and the solenoid; a manually operable switch for connecting the source of electrical power with the solenoid whereby the bar moves against the tension of the spring into operating position in which its contacts bridge said stationary contact whereby the bar is maintained in such position by the solenoid and the motor caused to run; a rheostat connected in series with the field of the motor, said rheostat including a contact movable in response to movement of the wire guiding means for gradually increasing the field strength of the motor to decrease its speed as the coil diameter increases; a motor stop auxiliary circuit connecting one side of the electric power source with a contact adjacent the rheostat and including an electro-magnet adjacent the solenoid control switch for opening the same, said contact being connected with the field of the motor by the movable contact of the rheostat when the same has moved through a predetermined cycle, whereby the electro-magnet is energized and the solenoid control switch opened so that the bar follows the tension of the spring whereupon the motor stops; and manually operable means for rendering the solenoid ineffective.
6. A coil winding machine comprising, in combination, a winding arbor, a wire supply spool holder; oscillating means for guiding wire from the supply spool in layers upon the arbor; an electric motor for operating the machine; a source of electric power; a movable bar carrying conductive contact bridges which are insulated from each other; a solenoid including a movable core for maintaining the bar in an operating position; a spring urging the bar from operating position into normal position; a plurality of stationary contacts which when bridged by the contacts of the bar connect the source of electric power with the field of the motor, the armature of the motor and the solenoid; a manually operable switch for connecting the source of electrical power with the solenoid whereby the bar moves against the tension of the spring into operating position in which its contacts bridge said stationary contacts whereby the bar is maintained in such position by the solenoid and the motor caused to run; a rheostat connected in series with the field of the motor; said rheostat including a contact movable in response to movement of the wire guiding means for gradually increasing the field strength of the motor to decrease its speed as the coil diameter increases; a motor stop auxiliary circuit connecting one side of the electric power source with a stationary contact adjacent the rheostat and including an electromagnet adjacent the solenoid control switch for opening the same, said stationary contact being connected with the field of the motor by the movable contact of the rheostat when the same has moved
- out of engagement with the rheostat, whereby the electro-magnet is energized and the solenoid control switch opened so that the bar follows the tension of the spring whereupon the motor stops; and manually operable means for rendering the solenoid ineffective.
7. A coil winding machine comprising, in combination, a winding arbor; a wire supply spool holder, oscillating means for guiding wire from the supply spool in layers upon the arbor; an electric motor for operating the machine; a source of electric power; a movable bar carrying conductive contact bridges which are insulated from each other; a solenoid including a movable core for shifting the bar in one direction; a spring urging the bar in the other direction; a plurality of stationary contacts which when bridged by the contacts of the bar connect the source of electric power with the field of the motor, the armature of the motor and the solenoid; a manually operable switch for connecting the source of electric power with the solenoid whereby the bar moves against the tension of the spring into an operating position in which its contacts bridge said stationary contacts whereby the bar is maintained in such position by the solenoid; a normally yieldingly closed solenoid control switch connected in series with the field of the motor, said switch including a stationary arcuate contact and another contact engaging and intermittently moving over said arcuate contact in response to the movement of the wire guide; a motor stop auxiliary circuit connecting one side of the electric power source with a stationary contact adjacent the arcuate contact and including an electro-magnet adjacent the solenoid control switch for opening the same, said stationary contact being connected with the field of the motor by said movable contact when the same moves into engagement with said stationary contact, whereby the electro-magnet is energized and the solenoid control switch opened so that the bar follows the tension of the spring whereupon the motor stops; manually operable means for rendering the solenoid ineffective; and a switch held open by the tension of the wire between the supply spool and the arbor, said switch being closed when the tension of the wire is removed whereby the solenoid control switch is connected in parallel with the electro-magnet thereby effecting the stopping of the motor.
8. A coil winding machine comprising, in combination, a winding arbor; a wire supply spool holder, oscillating means for guiding wire from the supply spool in layers upon the arbor; an electric motor for operating the machine; a source of electric power; a movable bar carrying conductive contact bridges which are insulated from each other; a solenoid including a movable core for shifting the bar in one direction; a spring urging the bar in the other direction; a plurality of stationary contacts which when bridged by the contacts of the bar connect the source of electric power with the field of the motor, the armature of the motor and the solenoid; a manually operable switch for connecting the source of electric power with the solenoid whereby the bar moves against the tension of the spring into an operating position in which its contacts bridge said stationary contacts whereby the bar is maintained in such position by the solenoid; a normally yieldingly closed solenoid control switch connected in series with said solenoid; a rheostat connected in series with

the field of the motor, said rheostat including a contact movable in response to movement of the wire guiding means for gradually increasing the field strength of the motor to decrease its speed 5 as the coil diameter increases, a motor stop auxiliary circuit connecting one side of the electric power source with a stationary contact adjacent the rheostat and including an electro-magnet adjacent the solenoid control switch for 10 opening the same, said stationary contact being connected with the field of the motor by said movable contact of the rheostat when the same moves into engagement with said stationary contact after a predetermined cycle of movement, 15 whereby the electro-magnet is energized and the solenoid control switch opened so that the bar follows the tension of the spring whereupon the motor stops; manually operable means for rendering the solenoid ineffective; and a switch 20 held open by the tension of the wire between the supply spool and the arbor, said switch being closed when the tension of the wire is removed whereby the solenoid control switch is connected in parallel with the electro-magnet thereby effecting the stopping of the motor. 25

9. A coil winding machine comprising, in combination, a winding arbor; a wire supply spool holder; oscillating means for guiding wire from the supply spool in layers upon the 30 arbor; an electric motor for operating the machine either to unwind wire from the supply spool and wind the same upon the arbor or to unwind the arbor and rewind the wire upon the supply spool; a source of electric power; a movable bar carrying conductive contact bridges which are insulated from each other; two solenoids including a movable core for maintaining the bar in either of two operating positions; a spring urging the bar from either operating position into a normal position; a plurality of stationary contacts which when bridged by the contacts of the bar in one operating position connect the source of electric power with the field of the motor, the armature of the motor and one of the solenoids; a manually operable switch for connecting the source of electric power with said one of the solenoids whereby the bar moves against the tension of the spring into one operating position, in which its contacts bridge said stationary contacts whereby the bar is maintained in such operating position by said one of the solenoids and the motor is caused to run; a plurality of stationary contacts displaced from the first mentioned stationary contacts and when bridged by the contacts of the bar in the other operating position connect the electric power source with the other solenoid, the field of the motor and the armature 45 of the motor whereby the polarity of the armature is reversed and hence the motor is reversed; manually operable means for connecting said other solenoid with the electric power source for shifting the bar into said other operating position; and manually operable means for rendering either solenoid ineffective. 50

10. A coil winding machine comprising, in combination a winding arbor; a wire supply spool holder; oscillating means for guiding wire from the supply spool in layers upon the arbor; an electric motor for operating the machine either to unwind wire from the supply spool and wind the same upon the arbor or to unwind the arbor and rewind the wire upon the supply spool; a source 55 of electric power; a movable bar carrying conductive contact bridges which are insulated from each other; two solenoids including a movable core for maintaining the bar in either of two operating positions; a spring urging the bar from either operating position into a normal position, a

plurality of stationary contacts which when bridged by the contacts of the bar in one operating position connect the source of electric power with the field of the motor, the armature of the motor and one of the solenoids; a manually operable switch for connecting the source of electric power with said one of the solenoids whereby the bar moves against the tension of the spring into said one operating position; a plurality of stationary contacts displaced from the first mentioned stationary contacts and when bridged by the contacts of the bar in the other operating position connect the electric power source with the other solenoid, the field of the motor and the armature of the motor whereby the polarity of the armature is reversed and hence the motor is reversed; manually operable means for effecting movement of the bar from said one operating position into said other operating position; and manually operable means for rendering either solenoid ineffective. 10

11. A coil winding machine comprising, in combination, a winding arbor; a wire supply spool holder; oscillating means for guiding wire from the supply spool in layers upon the arbor; an electric motor for operating the machine either to unwind wire from the supply spool and wind the same upon the arbor or to unwind the arbor and rewind the wire upon the supply spool; a source of electric power; a movable bar carrying conductive contact bridges which are insulated from each other; two solenoids including a movable core for maintaining the bar in either of two operating positions; a spring urging the bar from either operating position into a normal position; a plurality of stationary contacts which when bridged by the contacts of the bar in one operating position connect the source of electric power with the field of the motor, the armature of the motor and one of the solenoids; manually operable means for effecting movement of the bar against the tension of the spring into one operating position, in which its contacts bridge said stationary contacts whereby the bar is maintained in such operating position by said one of the solenoids and the motor is caused to run; a plurality of stationary contacts displaced from the first mentioned stationary contacts and when bridged by the contacts of the bar in the other operating position connect the electric power source with the other solenoid, the field of the motor and the armature of the motor whereby the polarity of the armature is reversed and hence the motor is reversed; manually operable means for connecting said other solenoid with the electric power source for shifting the bar into said other operating position; and manually operable means for rendering either solenoid ineffective. 15

12. A coil winding machine comprising, in combination, a winding arbor; a wire supply spool holder; oscillating means for guiding wire from the supply spool in layers upon the arbor; an electric motor for operating the machine either to unwind wire from the supply spool and wind the same upon the arbor or to unwind the arbor and rewind the wire upon the supply spool; a source of electric power; a movable bar carrying conductive contact bridges which are insulated from each other; two solenoids including a movable core for maintaining the bar in either of two operating positions; a spring urging the bar from either operating position into a normal position, a plurality of stationary contacts which when bridged by the contacts of the bar in one operating position connect the source of electric power 20

- with the field of the motor, the armature of the motor and one of the solenoids; manually operable means for effecting movement of the bar against the tension of the spring into one operating position, in which its contacts bridge said stationary contacts whereby the bar is maintained in such operating position by said one of the solenoids and the motor is caused to run; a plurality of stationary contacts displaced from the first mentioned stationary contacts and when bridged by the contacts of the bar in the other operating position connect the electric power source with the other solenoid, the field of the motor and the armature of the motor whereby the polarity of the armature is reversed and hence the motor is reversed; manually operable means for effecting movement of the bar from said one operating position into said other operating position; and manually operable means for rendering either solenoid ineffective.
13. A coil winding machine comprising, in combination, a winding arbor; a wire supply spool holder; oscillating means for guiding wire from the supply spool in layers upon the arbor or for guiding unreeled windings from the arbor as governed by the direction of rotation of the arbor; an electric motor for operating the machine either to unwind wire from the supply spool and wind the same upon the arbor or to unwind the arbor and rewind the wire upon the supply spool; a source of electric power; a movable bar carrying conductive contact bridges which are insulated from each other; two solenoids including a movable core for maintaining the bar in either of two operating positions; a spring urging the bar from either operating position into a normal position; a plurality of stationary contacts which when bridged by the contacts of the bar in one operating position connect the source of electric power with the field of the motor, the armature of the motor and one of the solenoids; a manually operable switch for connecting the source of electric power with said one of the solenoids whereby the bar moves against the tension of the spring into said one operating position; a plurality of stationary contacts displaced from the first said stationary contacts and when bridged by the contacts of the bar in the other operating position connects the electric power source with the other solenoid, the field of the motor and the armature of the motor whereby the polarity of the armature is reversed and hence the motor is reversed; manually operable means for connecting said other solenoid with the electric power source for shifting the bar into said other operating position; a normally yieldingly closed solenoid control switch connected in series with either solenoid; a motor stop auxiliary circuit in parallel with the source of electric power, said circuit including a switch held open by the tension of the wire between the supply spool and the arbor and an electro-magnet adjacent the solenoid control switch for opening the latter when said wire tension switch is closed whenever the tension of the wire is removed; and manually operable means for rendering either solenoid ineffective.
14. A coil winding machine comprising, in combination, a winding arbor; a wire supply spool holder; oscillating means for guiding wire from the supply spool in layers upon the arbor or for guiding unreeled windings from the arbor as governed by the direction of rotation of the arbor; an electric motor for operating the machine gradually increasing the field strength of the motor to decrease its speed as the coil diameter increases or for gradually decreasing the field strength of the motor to increase its speed as the coil diameter decreases depending upon the direction of movement of the wire guiding means; and manually operable means for rendering either solenoid ineffective.
15. A coil winding machine comprising, in combination, a winding arbor; a wire supply spool holder; oscillating means for guiding wire from the supply spool in layers upon the arbor or for guiding unreeled windings from the arbor as governed by the direction of rotation of the arbor; an electric motor for operating the machine either to unwind wire from the supply spool and wind the same upon the arbor or to unwind the arbor and rewind the wire upon the supply spool; a source of electric power; a movable bar carrying conductive contact bridges which are insulated from each other; two solenoids including a movable core for maintaining the bar in either of two operating positions; a spring urging the bar from either operating position into a normal position; a plurality of stationary contacts which when bridged by the contacts of the bar in one operating position connect the source of electric power with the field of the motor, the armature of the motor and one of the solenoids; a manually operable switch for connecting the source of electric power with said one of the solenoids whereby the bar moves against the tension of the spring into said one operating position; a plurality of stationary contacts displaced from the first said stationary contacts and when bridged by the contacts of the bar in the other operating position connects the electric power source with the other solenoid, the field of the motor and the armature of the motor whereby the polarity of the armature is reversed and hence the motor is reversed; manually operable means for connecting said other solenoid with the electric power source for shifting the bar into said other operating position; a normally yieldingly closed solenoid control switch connected in series with either solenoid; a motor stop auxiliary circuit in parallel with the source of electric power, said circuit including a switch held open by the tension of the wire between the supply spool and the arbor and an electro-magnet adjacent the solenoid control switch for opening the latter when said wire tension switch is closed whenever the tension of the wire is removed; and manually operable means for rendering either solenoid ineffective.
16. A coil winding machine comprising, in combination, a winding arbor; a wire spool holder; an arm operated by the pulling of wire from the spool to unwind wire therefrom as the wire is wound upon the arbor; means for rotating the arbor in a certain direction to wind wire thereon; means for rotating the arbor in the reverse direction to unwind wire therefrom; and means actuated in response to reversed rotation of the arbor only for operating the arm in the reverse direction to rewind wire upon the spool.
17. A coil winding machine comprising, in combination, a winding arbor; a wire spool holder; an arm operated by the pulling of wire from the spool to unwind wire therefrom as the wire is wound upon the arbor; means for rotating the arbor in a certain direction to wind wire thereon; and manually operable means for concurrently rotating the arbor in the reverse direction to unwind wire therefrom and operating the arm in the reverse direction to rewind wire upon the spool.
18. A coil winding machine comprising, in combination, a winding arbor; a wire spool holder; an arm operated by the pulling of wire from the spool to unwind wire therefrom as the wire is wound upon the arbor; power operated means for rotating the arbor in a certain direction so as to wind wire thereon; means for reversing the direction of motion of the power operated means in order to reverse the direction of rotation of the arbor so as to unwind wire therefrom; and a mechanism actuated in response to reversed rotation of the arbor for driving the arm in re-

verse direction so as to rewind wire upon the spool.

18. A coil winding machine comprising, in combination, a winding arbor; a wire spool holder; an arm operated by the pulling of wire from the spool to unwind wire therefrom as the wire is wound upon the arbor; power operated means for rotating the arbor in a certain direction so as to wind wire thereon; means for reversing the direction of motion of the power operated means in order to reverse the direction of rotation of the arbor so as to unwind wire therefrom; a mechanism for operating said arm in reverse direction to rewind wire upon the spool; a drive between the arbor and the arm operating mechanism, said drive being operative in response to reversed rotation of the arbor; and manually operable means for actuating the drive thereby concurrently operating said arm in said reverse direction and rotating the arbor in said reverse direction.

19. A coil winding machine comprising in combination, a winding arbor; a wire spool holder, a power driven shaft for rotating the winding arbor to wind wire thereon; means for stopping rotation of the shaft in wire winding direction; a mechanism for rewinding wire upon the spool while being unwound from the arbor, said mechanism being operative only when the arbor rotates in a reverse direction; a one way clutch drive between the said mechanism and the arbor; and manually operable means for driving one of the clutch halves in such direction that the mechanism is operated and the winding arbor reversely rotated.

20. A coil winding machine comprising in combination, a winding arbor; a wire spool holder; a power driven shaft for rotating the winding arbor to wind wire thereon; means for stopping rotation of the shaft in wire winding direction; a mechanism for rewinding wire upon the spool while being unwound from the arbor, said mechanism being operative only when the arbor rotates in a reverse direction; a one way clutch drive between the said mechanism and the arbor; a clutch having a stationary and a movable clutch half, the stationary clutch half being rotatable with the one way clutch; and means for moving the movable clutch half into driving engagement with the stationary clutch half and for rotating the movable clutch half in such direction that the operation of said mechanism and reversed rotation of the arbor is effected.

21. A coil winding machine comprising, in combination, a winding arbor; a wire spool holder frictionally resisting the unwinding of wire from the spool; a power driven shaft for rotating the winding arbor in either direction; means for stopping rotation of the power shaft in either direction; means for reversing the direction of rotation of the power shaft; a mechanism for rewinding wire upon the spool while being unwound from the arbor; a one way clutch for transmitting motion to said mechanism in order to operate the same only when the power shaft rotates in a direction to unwind wire from the arbor; a driving connection between the power shaft and the driving clutch half of said one way clutch; a clutch having a stationary and a movable clutch half, the stationary clutch half being rotatable with the driving clutch half of the one way clutch and the movable clutch half being normally yieldingly held out of engagement with the stationary clutch half; and means for moving the movable clutch half into driving engage-

ment with the stationary clutch half and for rotating the movable clutch half in such direction that operation of the mechanism and rotation of the arbor to unwind wire therefrom is effected.

22. A coil winding machine comprising, in combination, a winding arbor; a wire spool holder; an arm operated by the pulling of wire from the spool to unwind wire therefrom as the wire is wound upon the arbor; a power shaft for rotating the arbor; an electric motor for driving said shaft; means for controlling the motor so that it will drive the shaft in a normal direction to cause wire to be wound upon the arbor and for reversing the motor so that it drives the shaft in the reverse direction to cause wire to be unwound from the arbor; a mechanism for operating the arm in the reverse direction to rewind wire upon the spool; a permanently connected one way clutch drive between the power shaft and said mechanism whereby said drive is operable in response to reversed rotation of the power shaft; and manually operable means for operating said one way clutch drive so that the same reversely rotates the power shaft.

23. A coil winding machine comprising, in combination, a winding arbor; a wire spool holder; an arm operated by the pulling of the wire from the spool to unwind wire therefrom as the wire is wound upon the arbor; a power driven shaft; an arbor rotating device driven by said shaft; a mechanism for operating the arm in a direction to rewind wire upon the spool; a permanently connected one way clutch between the power shaft and mechanism in order to actuate said mechanism only when the power shaft is reversely rotating; and manually operable means for transmitting motion to said clutch so that the same reversely rotates the power shaft and actuates said mechanism.

24. A coil winding machine comprising, in combination, a winding arbor; a wire spool holder providing a bearing centrally of the spool; a hollow spindle journaled in said bearing; a shaft journaled in said spindle and frictionally connected therewith; an arm attached to the shaft and operated by the pulling of the wire from the spool to unwind wire therefrom as the wire is wound upon the arbor; a prime mover for rotating the arbor, said prime mover being reversible so as to rotate the arbor to unwind wire therefrom; and a mechanism operating in response to reversed rotation of the arbor to drive said spindle, shaft and arm, the friction drive between the spindle and shaft serving as a wire tension brake while the arm moves to unwind wire from the spool, the spindle then being stationary.

25. A coil winding machine comprising in combination, a winding arbor; means for guiding wire in layers upon the arbor, an electric motor for driving the machine; a motor speed control rheostat having a resistor and a movable contact; and means for operating the movable contact intermittently before beginning to wind an additional layer in order to decrease the motor speed.

26. A coil winding machine comprising, in combination, a winding arbor; means for guiding wire in layers upon the arbor; an electric motor for driving the machine; a motor speed control rheostat having a resistor and a movable contact; and means for operating the movable contact intermittently before beginning to wind an additional layer in order to decrease the motor speed and a device for stopping the mo-

tor in response to movement of said movable contact into a certain position.

27. A coil winding machine comprising, in combination, a winding arbor; means for guiding wire in layers thereon; an electric motor for driving the machine; and means for intermittently decreasing the speed of the motor before starting to wind the next layer of wire, said means also stopping the motor in timed relation with the complete winding of a predetermined number of layers upon the arbor.

28. A coil winding machine comprising, in combination, a winding arbor; reciprocable means for guiding wire in layers thereon; an electric motor for driving the machine; means for decreasing the speed of the motor before starting to wind additional layers of wire and for stopping the motor automatically after winding a certain number of layers upon the arbor, said means including stationary members and a co-operating movable member, the movable member being intermittently moved between the winding of layers of wire in response to reciprocation of the wire guiding means.

29. A coil winding machine comprising, in combination, a winding arbor; a wire supply spool holder; means for guiding wire from the spool to the arbor so that wire will be wound thereon in layers; means for unreeling wire from the spool as it is wound upon the arbor; an electric motor for driving the machine; electric means for intermittently varying the field current of the motor independently of its armature current so as to decrease the speed of the motor in order to decrease the rotary speed of the arbor, said means including stationary members and a co-operating movable member; and means for stopping the motor automatically after winding a certain number of layers upon the arbor, said means including coacting parts one of which is movable relative to the other, the movable part being the movable member of the field current varying means.

30. A coil winding machine comprising, in combination, a winding arbor; a wire supply spool holder; means for guiding wire from the spool to the arbor so that wire will be wound thereon in layers; means for unreeling wire from the spool as it is wound upon the arbor; means for rewinding wire upon the spool in response to reversed rotation of the arbor so as to unwind wire therefrom; manually operable means for reversely rotating the arbor; an electric motor for driving the machine; means for stopping the motor automatically when the wire breaks regardless of the direction of movement of the wire; and means for intermittently decreasing the speed of the motor before starting to wind an additional layer of wire.

31. A coil winding machine comprising, in combination, a winding arbor; a wire supply spool holder; means for guiding wire from the spool to the arbor so that wire will be wound thereon in layers; means for unreeling wire from the spool as it is wound upon the arbor; means for rewinding wire upon the spool in response to reversed rotation of the arbor so as to unwind wire therefrom; manually operable means for reversely rotating the arbor; an electric motor for driving the machine; means for stopping the motor automatically when the wire breaks regardless of the direction of movement of the wire; means for intermittently varying the field current of the motor independently of its armature current so as to decrease the speed of the motor in order

to decrease the rotary speed of the arbor, said means including stationary members and a co-operating movable member; and means for stopping the motor automatically after winding a certain number of layers upon the arbor, said means including coacting parts, one of which is movable relative to the other, the movable part being the movable member of the field current varying means.

32. A coil winding machine comprising, in combination, a winding arbor; a wire supply spool holder; means for guiding wire from the spool to the arbor so that wire will be wound thereon in layers; means for unreeling wire from the spool as it is wound upon the arbor and for rewinding wire upon the spool in response to reversed rotation of the arbor while unwinding wire therefrom; an electric motor for driving the machine; manually operable means for starting, stopping or reversing the motor; means for intermittently decreasing the speed of the motor before starting to wind an additional layer of wire, said means including coacting parts one of which is intermittently movable relative to the other; and means for automatically stopping the motor after winding a certain number of layers upon the arbor, said means including coacting parts one of which is movable relative to the other, said movable part being the movable member of the motor speed decreasing means.

33. A coil winding machine comprising, in combination, a winding arbor; a wire supply spool holder; means for guiding wire from the spool to the arbor so that wire will be wound thereon in layers; means for unreeling wire from the spool as it is wound upon the arbor and for rewinding wire upon the spool in response to reversed rotation of the arbor so as to unwind wire therefrom; an electric motor for driving the machine; manually operable means for starting, stopping or reversing the motor; means for stopping the motor automatically when the wire breaks regardless of the direction of movement of the wire; means for intermittently decreasing the speed of the motor before starting to wind an additional layer of wire, said means including stationary members, and a coacting movable member, and a switch for automatically effecting the opening of the motor circuit after the winding of a certain number of layers upon the arbor, said movable member of the motor speed decreasing means constituting the movable contact of said switch.

34. A coil winding machine comprising, in combination, a winding arbor; paper gripper bars yieldingly urged toward the arbor and adapted to feed a sheet of paper into engagement with the rotating arbor at each start of a new layer of wire; a pawl latching the gripper bars in a position most remote from the arbor; means for withdrawing the pawl from latching engagement with the gripper bars; means for guiding wire upon the arbor in layers or for guiding the unreeled layers on the arbor away therefrom depending upon the direction of rotation of the arbor, said means including a device movable parallel to the arbor axis, said device having projections adapted to operate the pawl withdrawing means upon engagement with the same; mechanisms for feeding the device relatively slowly in both directions, respectively; a member for transmitting motion from either of said mechanisms to said device and mounted to move laterally alternately into engagement with either of said mechanisms, and movable longitudinally when fed by either of

- said mechanisms; means for effecting the lateral shifting of said member after a certain amount of longitudinal shifting has taken place, said means including spring urged devices respectively operating during the longitudinal shifting of said member to store energy in a spring during the winding of layers upon the arbor only; a stop member engaged by said device during either of its longitudinal movements for the purpose of preventing the shifting of the device until after a certain longitudinal movement thereof has taken place; means operating upon the device to guide the same in a certain path while being shifted; and manually operable means for shifting the member laterally against the tension of the spring urged devices when the mechanisms are reversely operated for the purpose of unreeling layers from the arbor.
35. A coil winding machine comprising, in combination, a winding arbor; a wire spool holder frictionally resisting the unwinding of wire from the spool; a power driven shaft for rotating the winding arbor to wind wire thereon; means for stopping rotation of the power shaft in wire winding direction; a mechanism for rewinding wire upon the spool while being unwound from the arbor, said mechanism being operative only when the arbor rotates in reverse direction; a one way clutch drive between the said mechanism and the arbor; means for guiding wire upon the arbor in layers or for guiding the unreeled layers on the arbor away therefrom depending upon the direction of rotation of the arbor, said means including a bar movable parallel to the arbor axis; a mechanism operating when the arbor rotates for oscillating said bar and comprising a carrier member carrying oppositely facing half nuts, parallel feed screws each engageable with one of said nuts and cooperating respectively therewith to feed the nuts in opposite directions; devices yieldingly shifting the nut carrier laterally with respect to the feed screws automatically at the end of a predetermined travel of the nut carrier along the screws during the winding of layers of wire upon the arbor only, whereby one nut is disengaged from one of the feed screws and the other nut is engaged with the other feed screw; means for positively guiding the nut carrier during the lateral shifting of the nut carrier; manually operable means for shifting the nut carrier laterally with respect to the feed screws in the reverse direction when the feed screws are reversely rotated; a driving connection between the feed screws and the arbor; and manually operable means for driving one of the clutch halves of the one way clutch in such direction that the operation of the rewinding mechanism, reversed rotation of the arbor and reversed rotation of the feed screws is concurrently effected.
60. 36. A coil winding machine comprising, in combination, a winding arbor; a wire spool holder frictionally resisting the unwinding of wire from the spool; a power driven shaft for rotating the winding arbor in either direction; means for stopping rotation of the power shaft in either direction; means for reversing the direction of rotation of the power shaft; a mechanism for rewinding wire upon the spool while being unwound from the arbor; a one way clutch for transmitting motion to said mechanism to operate the same only when the power shaft rotates in a direction to unwind wire from the arbor; a driving connection between the power shaft and the driving clutch half of said one way clutch; means for guiding wire upon the

arbor in layers or for guiding the unreeled layers on the arbor away therefrom depending upon the direction of rotation of the arbor, said means including a bar movable parallel to the arbor axis; a mechanism operating when the arbor rotates for oscillating said bar and comprising a carrier member carrying oppositely facing half nuts, parallel feed screws each engageable with one of said nuts and cooperating respectively therewith to feed the nuts in opposite directions, and devices yieldingly shifting the nut carrier laterally with respect to the feed screws automatically at the end of a predetermined travel of the nut carrier along the screws during the winding of the layers of wire upon the arbor only, whereby one nut is disengaged from one of the feed screws and the other nut is engaged with the other feed screw; means for positively guiding the nut carrier during the lateral shifting of the nut carrier; manually operable means for shifting the nut carrier laterally with respect to the feed screws in the reverse direction when the feed screws are reversely rotated; a driving connection between the feed screws and the arbor; a clutch having a stationary and a movable clutch half, the stationary clutch half being rotatable with the driving clutch half of the one way clutch and the movable clutch half being normally yieldingly held out of engagement with the stationary clutch half; and means for moving the movable clutch half into driving engagement with the stationary clutch half and for rotating the movable clutch half in such direction that operation of the rewinding mechanism, rotation of the arbor to unwind wire therefrom and reversed rotation of the feed screws is concurrently effected.

37. A coil winding machine comprising, in combination, a winding arbor; a wire spool holder frictionally resisting the unwinding of wire from the spool; a power driven shaft for rotating the winding arbor to wind wire thereon; means for stopping rotation of the power shaft in wire winding direction; a mechanism for rewinding wire upon the spool while being unwound from the arbor, said mechanism being operative only when the arbor rotates in a reverse direction; a one way clutch drive between the said mechanism and the arbor; means for guiding wire upon the arbor in layers or for guiding the unreeled layers on the arbor away therefrom depending upon the direction of rotation of the arbor, said means including a bar movable parallel to the arbor axis; a mechanism operating when the arbor rotates for oscillating said bar and comprising a carrier member carrying oppositely facing half nuts, parallel feed screws each engageable with one of said nuts and cooperating respectively therewith to feed the nuts in opposite directions and devices yieldingly shifting the nut carrier laterally with respect to the feed screws automatically at the end of a predetermined travel of the nut carrier along the screws during the winding of layers of wire upon the arbor only, whereby one nut is disengaged from one of the feed screws and the other nut is engaged with the other feed screw; means for positively guiding the nut carrier during the lateral shifting of the same; manually operable means for shifting the nut carrier laterally with respect to the feed screws in the reverse direction when the feed screws are reversely rotated; a change speed driving connection between the feed screws and the arbor; manually operable means for changing the ratio of the driving connection; and manually operable means for driving one of the clutch halves of the one way clutch in

such direction that the operation of the rewinding mechanism, reversed rotation of the arbor and reversed rotation of the feed screws is concurrently effected.

- 5 38. A coil winding machine comprising, in combination, a winding arbor; a wire spool holder frictionally resisting the unwinding of wire from the spool; a power driven shaft for rotating the winding arbor to wind wire thereon; means for 10 stopping rotation of the power shaft in wire winding direction; a mechanism for rewinding wire upon the spool while being unwound from the arbor, said mechanism being operative only when the arbor rotates in a reverse direction; a one way 15 clutch drive between the said mechanism and the arbor; means for guiding wire upon the arbor in layers or for guiding the unreeled layers away from the arbor depending upon the direction of rotation of the arbor, said means including a bar 20 movable parallel to the arbor axis; a mechanism operating when the arbor rotates for oscillating said bar and comprising a carrier member carrying oppositely facing half nuts, parallel feed screws each engageable with one of said nuts and 25 cooperating respectively therewith to feed the nuts in opposite directions and devices yieldingly shifting the nut carrier laterally with respect to the feed screws automatically at the end of a predetermined travel of the nut carrier along the 30 screws during the winding of layers of wire upon the arbor only, whereby one nut is disengaged from one of the feed screws and the other nut is engaged with the other feed screw; means for positively guiding the nut carrier during the 35 lateral shifting of the nut carrier; manually operable means for shifting the nut carrier laterally with respect to the feed screws in the reverse direction when the feed screws are reversely rotated; a change speed driving connection between 40 the feed screws and the arbor; manually operable means for changing the ratio of the driving connection; a clutch having a stationary and a movable clutch half, the stationary clutch half being rotatable with the driving clutch half of the one 45 way clutch and the movable clutch half being normally yieldingly held out of engagement with the stationary clutch half; and means for moving the movable clutch half into driving engagement with the stationary clutch half and for rotating the movable clutch half in such direction that operation of the rewinding mechanism, rotation of the arbor to unwind wire therefrom and reversed rotation of the feed screws is concurrently effected.
- 55 39. In a coil winding machine, the combination of a rotatable winding arbor; means for guiding wire thereon; a pair of separable gripper bars movable together laterally with respect to the arbor and having companion ridge and groove surfaces between which a sheet of paper is located, the foremost edge of the sheet being in close proximity to the arbor and the wire being wound thereon but out of contact therewith when the gripper bars are in a position most remote from the arbor; and means for moving the gripper bars with the paper gripper between the ridge and groove surfaces into a position adjacent the arbor in which the foremost edge of the sheet is caught between the rotating arbor and the wire being wound thereon.
- 60 40. A coil winding machine comprising, in combination, a coil winding arbor; means for guiding wire in layers thereon; means for holding a sheet of paper to be wound upon the arbor with one 65 edge of the paper in close proximity to the arbor

and the wire being wound thereon but out of contact therewith; a pair of relatively movable gripper bars between which the paper passes; means for guiding the bars for movement together laterally with respect to the arbor; and means for 5 moving the bars toward the arbor with the paper gripped between them, said bars having companion, longitudinally extending ridge-and-groove surfaces which operate to move the paper toward the arbor while permitting the paper to be pulled 10 through said grippers by the rotating arbor, said ridge-and-groove surfaces operating to remove wrinkles from the paper.

41. A coil winding machine comprising, in combination, a rotatable coil winding arbor; means 15 for guiding wire in layers thereon; means for supporting a sheet of paper with the foremost edge of the paper in close proximity to the arbor and the wire being wound thereon but out of contact therewith; a pair of separable paper gripper 20 bars between which the paper passes; means for guiding the bars for movement together laterally with respect to the arbor; means for separating the bars in a position adjacent the arbor; means for moving the separated bars away from the 25 arbor and for causing them to grip the paper after a predetermined movement of the bars away from the arbor; and means for moving the bars toward the arbor.

42. A coil winding machine comprising, in 30 combination, a rotatable coil winding arbor; means for guiding wire in layers thereon; means for holding a sheet of paper with the foremost edge of the paper in close proximity to the arbor and the wire being wound thereon but out 35 of contact therewith; a pair of yieldingly separable gripper bars between which the paper passes; means for guiding the bars for movement together laterally with respect to the arbor; springs urging the bars toward the arbor; means 40 for separating the bars to permit the fed paper to pass between the bars; means for maintaining the bars separated; means for retracting the bars, while separated, away from the arbor and for causing them to grip the paper at the end 45 of such retracting movement; means for latching the bars against the action of the springs in the position most retracted from the arbor; and means for releasing the bars to permit the springs to move the bars and paper together toward the 50 arbor.

43. A coil winding machine comprising, in combination, a rotatable coil winding arbor; a pair of yieldingly separable gripper bars movable together laterally with respect to the arbor, said bars holding between their engaging surfaces, while in a position remote from the arbor, a sheet of paper, the foremost edge of which is in close proximity to the arbor and the wire being wound 60 thereon; means for moving the bars while gripping toward the arbor; means for separating the bars while in a position adjacent the arbor and for maintaining the same separated until the bars reach remote position in order to permit 65 the introduction of a sheet of paper between the bars; and means for retracting the bars from the arbor.

44. A coil winding machine comprising, in combination, a rotatable coil winding arbor; 70 means for guiding wire in layers thereon; a pair of yieldingly separable gripper bars movable together laterally with respect to the arbor, said bars holding between their engaging surfaces while in a position remote from the arbor a 75

- sheet of paper, the foremost edge of which is in close proximity to the arbor; means yieldingly urging the bars toward the arbor; means latching the bars in remote position; means for releasing the latching means from the bars whereupon the latter while gripping move the foremost edge of the sheet into engagement with the rotating arbor and the wire being wound thereon; means for separating the bars while in a position adjacent the arbor and for maintaining the same separated until the bars reach remote position in order to permit the introduction of a sheet of paper between the bars; and means for retracting the bars from the paper.
- 15 45. A coil winding machine comprising, in combination, a rotatable coil winding arbor; reciprocable means for guiding wire in layers thereon; a pair of paper gripper bars having undulated surfaces receiving therebetween a sheet of paper with the foremost edge thereof in close proximity to the arbor; means for guiding the bars for movement together laterally with respect to the arbor; means for retracting the bars from the arbor and for causing the bars to grip a new sheet of paper with their undulated surfaces during the latter part of such retracting movement; means for causing the bars quickly to approach the arbor automatically upon the completion of a layer of turns so that the foremost edge of the paper is caught between the rotating arbor and the wire being wound thereon whereupon the paper is pulled through the gripping undulated surfaces of the bars thereby removing wrinkles in the paper; and means operated in response to reciprocation of the wire guiding means for separating the bars in the position adjacent the arbor in order to permit the introduction between the bars of a sheet of paper.
- 40 46. A coil winding machine comprising, in combination, a rotatable coil winding arbor; reciprocable means for guiding wire in layers thereon; a pair of gripper bars having undulated surfaces receiving therebetween a sheet of paper with the foremost edge thereof in close proximity to the arbor; means for guiding the bars for movement together laterally with respect to the arbor; spring means urging the bars toward the arbor; means for separating the bars; means for retracting the bars, while separated, away from the arbor in order to permit the introduction between the bars of a sheet of paper; means for causing the bars to grip the paper toward the end of such retracting movement; means for latching the bars against the action of the springs in the position most remote from the arbor; and means for releasing the bars to permit the springs to move the bars and paper together toward the arbor in response to movement of the wire guiding means into either end position so that the foremost edge of the paper is caught between the rotating arbor and the wire being wound thereon whereupon the paper is pulled through the gripping undulated surfaces of the bars thereby removing wrinkles in the paper.
- 45 47. A coil winding machine comprising, in combination, a rotatable coil winding arbor; means for guiding wire in layers thereon; a pair of yielding separable gripper bars movable together laterally with respect to the arbor, said bars holding between their engaging surfaces while in a position remote from the arbor a sheet of paper the foremost edge of which is in close proximity to the arbor and the wire being wound
- 50 thereon but out of contact therewith; means for moving the bars while gripping from remote position into a position adjacent the arbor in which position the foremost edge of the paper is caught between the rotating arbor and the wire being wound thereon; means for separating the bars in the position adjacent the arbor; means responsive to separation of the bars for maintaining the same separated until the bars reach remote position in order to permit the introduction of a sheet of paper between the bars; and means for moving the bars into remote position.
- 55 48. A coil winding machine comprising, in combination, a coil winding arbor; means for guiding wire in layers thereon; guideways; a pair of separable gripper bars normally yieldingly engaging each other and being together movable in said guideways in a direction laterally with respect to the arbor, one of said bars having laterally extending fingers and both bars holding between their engaging surfaces while in a position remote from the arbor a sheet of paper the foremost edge of which is in close proximity to the arbor and the wire being wound thereon but out of contact therewith; means for moving the bars while gripping from remote position into a position adjacent the arbor in which position the foremost edge of the paper is caught by the rotating arbor and the wire being wound thereon; spring urged latch members normally projecting into the path of movement of the projecting fingers when the bars are in gripping engagement, each member having a camming surface leading to a shoulder and both members being cammed out of the path of movement of the fingers by the latter during movement of the bars while gripping into the position adjacent the arbor in which position the fingers engage the shoulders of the members which prevent movement of the bars while gripping into remote position; means for separating the bars while in the position adjacent the arbor thereby moving the fingers out of engagement with the shoulders of the members whereupon the members return to normal position and maintain the bars separated until the latter during movement into remote position completely clear said members in order to permit the introduction of a sheet of paper between the bars; and means for moving the bars into remote position.
- 60 49. In a machine for winding coils, the combination of a winding arbor; an extensible apron; a roller upon which one end of the apron is wound; a spring urging the roller to wind up the apron; a member near the arbor; a movable member remote from the arbor, the free end of the apron being connected to one of these members and the roller being mounted on the other of said members; a paper knife supported by the movable member; a paper supply roll; and means for feeding paper from the supply roll between the blades of said knife and along said apron toward the arbor.
- 65 50. In a machine for winding coils, the combination of a winding arbor; an extensible apron; a roller upon which one end of the apron is wound; a spring urging the roller to wind up the apron; a member near the arbor; a movable member remote from the arbor, the free end of the apron being connected to one of the members and the roller being mounted on the other of the members; a paper supply roll; paper feed rolls supported by said movable member; and means for actuating the feed rolls in order to feed paper

- from the supply roll along the apron and toward the arbor.
51. In a machine for winding coils, the combination of a winding arbor; an extensible part 5 or apron; a roller upon which one end of the apron is wound; a spring urging the roller to wind up the apron; a member near the arbor to which the free end of the apron is connected; a movable carriage on which the roller is mounted; a paper knife supported by the carriage; a paper supply roll; and means for feeding paper from the supply roll between the blades of said knife and along 10 said apron.
52. In a machine for winding coils, the combination of a winding arbor; an extensible part 15 or apron; a roller upon which one end of the apron is wound; a spring urging the roller to wind up the apron; a reciprocable member near the arbor for gripping a sheet of paper and moving 20 the same toward the arbor; and a member remote from the arbor, the free end of the apron being attached to one of the members and the roller being mounted on the other member.
53. In a machine for winding coils, the combination of a winding arbor; an extensible part 25 or apron; a roller upon which one end of the apron is wound; a spring urging the roller to wind up the apron; reciprocable means near the arbor for gripping a sheet of paper and moving the 30 same into contact with the rotating arbor and the wire being wound thereon, the free end of the apron being attached to said means; a movable carriage remote from the arbor on which the roller is mounted; a paper knife supported by 35 the carriage; a paper supply roll; and means for feeding paper from the supply roll between the blades of said knife and along said apron into engagement with said gripping means.
54. In a machine for winding coils, the combination of a winding arbor; an extensible part or 40 apron; a roller upon which one end of the apron is wound; a spring urging the roller to wind up the apron; reciprocable means near the arbor for gripping a sheet of paper and moving the same 45 into contact with the rotating arbor and the wire being wound thereon, the free end of the apron being attached to said means; a movable carriage remote from the arbor and on which the roller is mounted; a paper knife supported by the carriage; a paper supply roll; paper feed rolls supported by the carriage; and means for actuating 50 the feed rolls so as to feed paper from the supply roll between the blades of said knife and along said apron into engagement with said gripping means.
55. In a coil winding machine, the combination of a coil winding arbor; means for guiding wire in 55 layers thereon; a paper supply roll holder; a knife carriage intermediate the paper supply roll and the arbor, said carriage being movable laterally with respect to the arbor; a paper cutting knife carried by the carriage; means for operating the knife in any position of the carriage; means for feeding paper from the supply roll past the knife and toward the arbor; means for intermittently retracting the carriage from the arbor as the coil diameter increases, said means including a chain fastened with both ends to the carriage and guided over sprocket wheels; and a common means for actuating the knife operating means and for indexing one of the sprocket wheels so as to intermittently retract the carriage.
56. In a coil winding machine, the combination of a coil winding arbor; means for guiding wire in 60 layers thereon; a paper supply roll holder; a knife carriage intermediate the paper supply roll and the arbor, said carriage being movable laterally with respect to the arbor; a paper cutting knife carried by the carriage; means for feeding paper from the supply roll past the knife and toward the arbor; means for intermittently retracting the carriage from the arbor as the coil diameter increases, said means including a chain fastened with both ends to the carriage and guided over sprocket wheels; shafts extending parallel to the direction of movement of the carriage; means on one of said shafts for actuating the

carriage intermediate the paper supply roll and the arbor, said carriage being movable laterally with respect to the arbor; a paper cutting knife carried by the carriage; means for operating the knife in any position of the carriage; means for feeding paper from the supply roll past the knife and toward the arbor; means for intermittently retracting the carriage as the coil diameter increases, said means including a chain fastened with both ends to the carriage and guided over sprocket wheels, a ratchet disc rotatable with one of said sprocket wheels and a pawl cooperating with the ratchet disc; and a common means for actuating the knife actuating means and for actuating the pawl so as to index the ratchet disc 15 in order to intermittently retract the carriage.

57. In a coil winding machine, the combination of a coil winding arbor; means for guiding wire in layers thereon; a paper supply roll holder; a knife carriage intermediate the paper supply roll 20 and the arbor, said carriage being movable laterally with respect to the arbor; a paper cutting knife carried by the carriage; means for operating the knife in any position of the carriage; means for feeding paper from the supply roll past 25 the knife and toward the arbor; means for moving the carriage toward and away from the arbor, said means including a chain fastened with both ends to the carriage and guided over sprocket wheels; means for rotating one of the sprocket 30 wheels in either direction; means for intermittently retracting the carriage from the arbor as the coil diameter increases, said means including a ratchet disc rotatable with one of the sprocket wheels and a movable pawl; normally yieldingly 35 urged against the ratchet teeth; means for moving the pawl so as to index the ratchet disc in order intermittently to retract the carriage, said means normally maintaining the pawl in a certain inoperative position; and a stop engaging 40 the pawl in said inoperative position only for maintaining the same out of engagement with the ratchet teeth in order not to interfere with movement of the carriage toward the arbor.

58. In a coil winding machine, the combination 45 of a winding arbor; means for guiding wire in layers thereon; a paper supply roll holder; a paper feed carriage intermediate the paper supply roll and the arbor, said carriage being movable laterally with respect to the arbor; frictionally 50 engaging paper feed rollers carried by the carriage for feeding paper from the supply roll toward the arbor; a manually rotatable shaft extending parallel to the direction of movement of the carriage; a gear splined to said shaft and movable with the carriage; another gear rotatable with one of the feed rollers and constantly meshing with the first mentioned gear; and means for moving the carriage toward or away from the arbor.

59. In a coil winding machine, the combination of a coil winding arbor; means for guiding wire in layers thereon; a paper supply roll holder; a knife carriage intermediate the paper supply roll and the arbor, said carriage being movable laterally with respect to the arbor; a paper cutting knife carried by the carriage; means for feeding paper from the supply roll past the knife and toward the arbor; means for intermittently retracting the carriage from the arbor as the coil diameter increases, said means including a chain fastened with both ends to the carriage and guided over sprocket wheels; shafts extending parallel to the direction of movement of the carriage; means on one of said shafts for actuating the

intermittent carriage retracting means upon rocking of said one shaft; means including levers splined to said shafts for actuating the knife in any position of the carriage upon rocking of said 5 shaft; and means for simultaneously rocking said shafts.

60. A coil winding machine comprising, in combination, a coil winding arbor; means for guiding wire in layers upon the arbor; a paper supply roll holder; a carriage movable laterally of the arbor; a paper knife mounted on the carriage and having blades between which the paper passes; a paper sheet holder extending between the knife carriage and arbor; means for feeding 10 paper from the supply roll between the knife blades and along the paper sheet holder and up to the arbor; means for cutting off the paper at the desired distance from the arbor as governed by the location of the carriage; means for feeding 15 the paper sheet to the arbor; means for moving the knife carriage away from the arbor as the coil diameter increases; manually operable means for moving the carriage toward the arbor; a stop 20 obstructing movement of the carriage only in a direction toward the arbor; and manually operable means for releasing the carriage from said stop.

61. A coil winding machine comprising, in combination, a coil winding arbor; means for guiding wire in layers upon the arbor; a paper supply roll holder; a carriage movable laterally of the arbor, said carriage having a movable finger; a paper knife mounted on the carriage and having blades between which the paper passes; a paper sheet holder extending between the knife carriage and arbor; means for feeding paper from the supply roller between the knife blades and along the paper sheet holder and up to the arbor; means for cutting off the paper at the desired 30 distance from the arbor as governed by the location of the carriage; means for feeding the cut paper to the arbor; means for moving the knife carriage away from the arbor as the coil diameter increases; manually operable means for 35 moving the carriage toward or away from the arbor; a stop obstructing movement of the carriage only in a direction toward the arbor, said stop including a spring pressed plate normally held at a certain distance from a stationary member of said stop, said spring pressed plate being moved by the finger of the forwardly moving carriage against the tension of the spring until engaged by the stationary member of said stop; and manually operable means for withdrawing the 40 movable finger of the carriage from the path of movement of the withdrawn spring pressed plate.

62. A coil winding machine comprising, in combination, a coil winding arbor; means for guiding wire in layers upon the arbor; a paper supply 45 roll holder; a carriage movable laterally of the arbor, said carriage having a movable finger, a paper knife mounted on the carriage and having blades between which the paper passes; a paper sheet holder extending between the knife carriage and arbor; means for feeding paper from the supply roller between the knife blades and along the paper sheet holder and up to the arbor; means for moving the knife carriage away 50 from the arbor as the coil diameter increases; manually operable means for moving the carriage toward or away from the arbor; means for feeding the paper sheet to the arbor, a stop obstructing movement of the carriage only in a direction 55 toward the arbor, said stop including a spring pressed plate normally held at a certain distance

from a stationary member of said stop, said spring pressed plate being moved by the finger of the forwardly moving carriage against the tension of the spring until engaged by said stationary member of the stop; and a manually operable member for simultaneously withdrawing the finger of the carriage from the path of movement of the withdrawn spring pressed plate of the stop and for cutting off the paper at the desired distance from the arbor as governed by the 60 location of the carriage.

63. A coil winding machine comprising, in combination, a coil winding arbor; means for guiding wire in layers thereon; a paper supply roll holder; a relatively stationary carriage; a paper knife 10 mounted on the carriage and having cutting blades; a paper sheet holder extending between the knife carriage and the arbor; a pair of cooperating rotatable paper feed rollers carried by the carriage for feeding paper from the supply 15 roll between the knife blades and along the paper sheet holder and up to the arbor; means for operating the knife in any position of the carriage; means for rotating the paper feed rollers in any 20 position of the carriage; a reciprocable device 25 for moving the cut paper from the sheet holder to the arbor; means for moving the device toward the arbor; means for retracting the device from the arbor; means for intermittently retracting the carriage from the arbor as the coil diameter 30 increases; and common operable means for actuating the knife operating means, the device retracting means and the intermittent carriage retracting means.

64. A coil winding machine comprising, in combination a rotatable coil winding arbor; means for guiding wire in layers thereon; means for holding a sheet of paper preparatory to feeding it to the arbor; a paper supply roll holder; means for feeding paper from the supply roll to the paper 40 sheet holding means with the foremost edge of the paper in close proximity to the arbor and the wire being wound thereon but out of contact therewith; means for cutting off the desired length of paper; a pair of gripper bars intermediate the 45 paper cutting means and the arbor; means for guiding the bars for movement together laterally with respect to the arbor; spring means urging the bars while gripping into a position adjacent the arbor so as to feed the foremost edge of the 50 cut paper between the rotating arbor and the wire being wound thereupon; means for separating the bars preceding the feeding of the new paper to the sheet holding means; means for retracting the bars, while separate, away from the arbor 55 and for releasing the separated bars to grip newly cut paper toward the end of such retracting movement; means for latching the bars against the action of the springs in the position most remote from the arbor; means for releasing the 60 bars while gripping to permit the springs to move the bars and paper together toward the arbor after the winding of a layer of turns of wire in order that the foremost edge of the paper is 65 caught between the rotating arbor and the wire being wound thereon; and a common operable member for simultaneously actuating the paper cutting means and the gripper bars retracting means.

65. A coil winding machine comprising, in combination, a rotatable coil winding arbor; reciprocable means for guiding wire in layers thereon; reciprocable paper conveying means, said means also holding a sheet of paper preparatory to feed- 70

- ing it to the arbor; a paper supply roll holder; a pair of cooperating paper feed rollers for feeding paper from the supply roll to the paper conveying means with the foremost edge of the paper in close proximity to the arbor and the wire being wound thereon; means for cutting off the desired length of paper; springs for moving the paper conveying means toward the arbor so as to move the foremost edge of the paper between the rotating arbor and wire to be wound thereupon; means for retracting the paper conveying means from the arbor against the action of the springs; means for latching the paper conveying means in retracted position; means for releasing said latching means, said releasing means being responsive to reciprocation of the wire guiding means; and a manually operable member for simultaneously actuating the paper cutting means and the means for retracting the paper conveying means.
66. A coil winding machine comprising, in combination, a rotatable coil winding arbor; means for guiding wire in layers thereon; a paper supply roll holder; a paper feed roller and knife carriage movable laterally with respect to the arbor between the arbor and paper supply roll; a pair of paper feed rollers supported by the carriage; means for rotating the rollers in any position of the carriage for concurrently pulling paper from the supply roll and feeding paper toward the arbor; a knife supported by the carriage for cutting the paper; manually operable means for operating the knife in any position of the carriage; means for retracting the carriage step-by-step from the arbor after a layer winding operation; a pair of normally yieldingly closed paper gripper bars intermediate the paper feed rollers and the arbor between which the fed paper passes and which hold the foremost edge of the paper in close proximity to the arbor and the wire being wound thereon; means for guiding the bars for movement together laterally with respect to the arbor, said bars when moving toward the arbor frictionally engaging the cut paper; spring means urging the closed bars toward the arbor so as to feed the foremost edge of the cut paper between the rotating arbor and the wire to be wound thereupon; means for separating the bars after the paper is caught between the arbor and the wire being wound thereon; and means for retracting the bars while separated away from the arbor before completion of a layer of turns, said means being operated in response to the actuation of the knife operating means.
67. A coil winding machine comprising, in combination, a rotatable coil winding arbor; means for guiding wire in layers thereon; a paper supply roll holder; a paper feed roller and knife carriage movable laterally with respect to the arbor and being located between the arbor and the paper supply roll; a pair of paper feed rollers supported by the carriage; means for operating the rollers in any position of the carriage for concurrently pulling paper from the supply roll and feeding the same toward the arbor; a knife supported by the carriage for cutting the paper; means for operating the knife in any position of the carriage; means for retracting the carriage step-by-step from the arbor after a layer winding operation, said means including a ratchet; a pair of separable gripper bars between which the fed paper passes and which hold the foremost edge of the paper in close proximity to the arbor and the wire being wound thereon; means for guiding the bars for movement together laterally with respect to the arbor; spring means urging the bars toward the arbor; means for separating the bars; means for retracting the bars, while separated, away from the arbor with the paper lying between them; means for causing the bars to grip the paper at the end of such retracting movement; means for latching the bars against the action of the springs in the position most remote from the arbor; means for releasing the bars to permit the springs to move the bars and paper together toward the arbor after the winding of a layer of turns of wire; and a manually operable member which when rocked in one direction operates the knife operating means and when rocked in the reverse direction indexes the ratchet thereby imparting to the carriage a step-by-step retracting movement.
68. A coil winding machine comprising, in combination, a machine frame; a rotatable coil winding arbor; means for guiding wire in layers thereon; a paper supply roll holder; a paper feed roller and knife carriage movable on the machine frame laterally with respect to the arbor and being located between the arbor and the paper supply roll; means for moving the carriage laterally with respect to the arbor, said means including a chain fastened with both ends to the carriage and guided over sprocket wheels; manually operable means for driving one of the sprocket wheels; a pair of paper feed rollers supported by the carriage; means for operating the rollers in any position of the carriage for concurrently pulling paper from the supply roll and feeding the same toward the arbor; a knife supported by the carriage for cutting the paper; means for operating the knife in any position of the carriage; means for retracting the carriage step-by-step from the arbor after a layer winding operation, said means including a ratchet which is rotatable in unison with one of the sprocket wheels; a pair of separable gripper bars between which the paper passes and which hold the foremost edge of the paper in close proximity to the arbor and the wire being wound thereon; means for guiding the bars for movement together laterally with respect to the arbor; spring means urging the bars toward the arbor; means for separating the bars; means for retracting the bars, while separated, away from the arbor with the paper lying between them; means for causing the bars to grip the paper at the end of such retracting movement; means for latching the bars against the action of the springs in the position most remote from the arbor; means for releasing the bars to permit the springs to move the bars and paper together toward the arbor after the winding of a layer of turns of wire; and a manually operable member which when rocked in one direction operates the knife operating means and when rocked in the reverse direction indexes the ratchet thereby imparting to the carriage a step-by-step retracting movement.
69. A coil winding machine comprising, in combination, a rotatable coil winding arbor; means for guiding wire in layers thereon; a paper supply roll holder; a paper feed roller and knife carriage movable laterally with respect to the arbor and being located between the arbor and the paper supply roll; a pair of paper feed rollers supported by the carriage; means for operating the rollers in any position of the carriage; a knife supported by the carriage for cutting the paper; means for operating the knife in any position of the carriage; means for retracting the carriage step-by-step from the arbor after a layer winding operation, said means including a ratchet; a pair of separable gripper bars between which the fed paper passes and which hold the foremost edge of the paper in close proximity to the arbor and the wire being wound thereon; means for guiding the bars for movement together laterally with respect to the arbor; spring means urging the bars toward the arbor; means for separating the bars; means for retracting the bars, while separated, away from the arbor with the paper lying between them; means for causing the bars to grip the paper at the end of such retracting movement; means for latching the bars against the action of the springs in the position most remote from the arbor; means for releasing the bars to permit the springs to move the bars and paper together toward the arbor after the winding of a layer of turns of wire; and a manually operable member which when rocked in one direction operates the knife operating means and when rocked in the reverse direction indexes the ratchet thereby imparting to the carriage a step-by-step retracting movement.

carriage step-by-step from the arbor after a layer winding operation, said means including a ratchet; a pair of separable gripper bars between which the fed paper passes and which hold the 5 foremost edge of the paper in close proximity to the arbor and the wire being wound thereon; means for guiding the bars for movement together laterally with respect to the arbor; spring means urging the bars toward the arbor; means for separating the bars; means for retracting the 10 bars, while separated, away from the arbor with the paper lying between them; means for causing the bars to grip the paper toward the end of such retracting movement; means for latching the 15 bars against the action of the springs in the position most remote from the arbor; means for releasing the bars to permit the spring to move the bars and paper together toward the arbor after the winding of a layer of turns of wire; a 20 manually operable member which when rocked from a normal position into an operating position actuates the knife operating means and the gripper bar retracting means, and which when released in the operating position indexes the 25 ratchet thereby imparting to the carriage a step-by-step retracting movement; and a spring for returning said member from the operating position into normal position.

70. A coil winding machine comprising, in combination, a rotatable coil winding arbor; means for guiding wire in layers thereon; a paper supply roll holder; a carriage movable laterally with respect to the arbor, said carriage having a movable finger; a paper knife mounted on the carriage and having blades between which the paper passes; means for feeding paper from the supply roll between the knife blades and toward the arbor; a pair of separable gripper bars between which the fed paper passes and which hold the foremost edge of the paper in close proximity to the arbor and the wire being wound thereon; means for guiding the bars for movement together laterally with respect to the arbor; spring means urging the bars toward the 45 arbor; means for separating the bars; means for retracting the bars, while separated, away from the arbor with the paper lying between them; means for causing the bars to grip the paper toward the end of such retracting movement; means for latching the bars against the action of the 50 springs in the position most remote from the arbor; means for releasing the bars to permit the springs to move the bars and paper together toward the arbor after the winding of a layer of 55 turns of wire; means for moving the knife carriage away from the arbor as the coil diameter increases; manually operable means for moving the carriage toward or away from the arbor; a stop obstructing movement of the carriage only 60 in a direction toward the arbor, said stop including a spring pressed plate normally held at a certain distance from a stationary member of said stop, said spring pressed plate being moved by the finger of the forwardly moving carriage 65 against the tension of the spring until engaged by said stationary member of the stop; and a manually operable member for simultaneously withdrawing the finger on the carriage from the path of movement of the withdrawn spring 70 pressed plate of the stop, for actuating the paper knife at the desired distance from the arbor as governed by the location of the carriage, and for actuating the gripper bar retracting means.

71. A coil winding machine comprising, in combination, a coil winding arbor; a wire guide

including an oscillating member movable along the arbor; an electric motor for operating the machine; and means responsive to movements of the wire guiding member for gradually increasing the field strength of the motor to decrease its speed whereby to decrease the angular speed of the arbor as the coil diameter increases. 5

72. A coil winding machine comprising, in combination, a coil winding arbor; a wire guide including an oscillating member movable along 10 the arbor; power means for operating the machine; and means responsive to movements of the wire guiding member for intermittently decreasing the angular speed of the arbor between the winding of layers of wire and for stopping the 15 power means after a predetermined number of oscillations of the member.

73. A coil winding machine comprising, in combination; a coil winding arbor, a wire guide including an oscillating member movable along 20 the arbor; an electric motor for operating the machine; a rheostat in the field circuit of the motor; and an intermittent motion mechanism operated in response to movements of the wire 25 guiding member for operating the rheostat for gradually increasing the field strength of the motor to decrease its speed whereby to decrease the angular speed of the arbor as the coil diameter increases.

74. A coil winding machine comprising in 30 combination, a coil winding arbor, a wire guide including an oscillating member movable along the arbor, an electric motor for operating the machine, means for stopping the motor including 35 a remote control switch having movable and stationary contacts; and an intermittent motion mechanism operated in response to movements of the wire guiding member for operating the movable contact finally into engagement with said stationary contact after a certain number 40 of layers of wire has been wound.

75. A coil winding machine comprising, in combination, a rotating arbor for simultaneously winding a plurality of coils thereon; reciprocal means for simultaneously guiding a plurality 45 of wires in layers upon the arbor; means for wrapping a sheet paper between successive layers of wire; and means actuated in response to reciprocation of the wire guiding means for cutting off those portions of the wrapped paper sheet 50 which extend beyond the ends of the layers of wire.

76. A coil winding machine comprising, in combination, a rotatable arbor for simultaneously winding a plurality of coils thereon; reciprocal 55 means for simultaneously guiding a plurality of wires in layers thereon; means for wrapping paper between successive layers of wire; a rotatable shaft extending parallel to the arbor; a plurality of brackets mounted on said shaft, said brackets being located adjacent the ends of the layers of wire and yieldingly carrying a cutting blade; and means actuated in response to reciprocation of the wire guiding means for rocking the shaft in such direction that the cutting blades 60 engage and cut off those portions of the wrapped paper extending beyond the ends of the layers of wire.

77. A coil winding machine comprising, in combination, a rotatable coil winding arbor; reciprocal means for guiding wire in layers thereon; a pair of yieldingly separable gripper bars movable together laterally with respect to the arbor, said bars holding between their engaging 70 surfaces while in a position remote from the 75

- arbor a sheet of paper the foremost edge of which is in close proximity to the arbor and the wire being wound thereon but out of contact therewith; means actuated in response to reciprocation of the wire guiding means for separating the bars while in a position adjacent the arbor and for maintaining the same separated until the bars reach remote position in order to permit the introduction of a sheet of paper between the bars; 5 means for retracting the bars from adjacent the arbor into remote position; and means for moving the bars while gripping from remote position into the position adjacent the arbor in which position the foremost edge of the paper is caught 10 between the rotating arbor and the wire being wound thereon.
78. A coil winding machine comprising in combination, a rotatable coil winding arbor; a reciprocable means for guiding wire in layers thereon; a pair of yieldingly separable gripper bars movable together laterally with respect to the arbor, said bars holding between their engaging surfaces while in a position remote from the arbor a sheet 15 of paper the foremost edge of which is in close proximity to the arbor and the wire being wound thereon but out of contact therewith; means actuated in response to reciprocation of the wire guiding means for separating the bars in a position adjacent the arbor; means for retracting the bars 20 from adjacent the arbor into remote position; means for maintaining the bars separated until the same reach remote position in order to permit the introduction of a sheet of paper between the bars; and means for moving the bars while gripping from remote position to the position adjacent 25 the arbor in which position the foremost edge of the paper is caught between the rotating arbor and the wire being wound thereon.
79. A coil winding machine comprising, in combination, a rotatable coil winding arbor; reciprocable means for guiding wire in layers thereon; a pair of yieldingly separable gripper bars movable together laterally with respect to the arbor, said bars holding between their engaging surfaces 30 while in a position remote from the arbor a sheet of paper the foremost edge of which is in close proximity to the arbor and the wire being wound thereon but out of contact therewith; means for moving the bars while gripping from remote position into a position adjacent the arbor in which position the foremost edge of the paper is caught between the rotating arbor and the wire being wound thereon; means actuated in response to reciprocation of the wire guiding means for separating the bars in the position adjacent the arbor; means responsive to separation 35 of the bars for maintaining the same separated until they reach remote position in order to permit the introduction of a sheet of paper between the bars; and means for moving the bars into remote position.
80. A coil winding machine comprising, in combination, a rotatable coil winding arbor; reciprocable means for guiding the wire in layers thereon; a pair of yieldingly separable gripper bars 40 movable together laterally with respect to the arbor, said bars holding between their engaging surfaces while in a position remote from the arbor a sheet of paper the foremost edge of which is in close proximity to the arbor and the wire being wound thereon but out of contact therewith; means actuated in response to reciprocation of the wire guiding means for separating the bars in a position adjacent the arbor; means responsive to separation 45 of the bars for maintaining the same separated until they reach remote position in order to permit the introduction of a sheet of paper between the bars; and means for moving the bars into remote position.
81. A coil winding machine comprising, in combination, a rotatable coil winding arbor; means for guiding wire in layers thereon; a pair of yieldingly separable gripper bars movable together laterally with respect to the arbor, said bars holding between their engaging surfaces while in a position remote from the arbor a sheet of paper the foremost edge of which is in close proximity to the arbor and the wire being wound thereon but out of contact therewith; means actuated in response to reciprocation of the wire guiding means for releasing the latching means from the bars whereupon the latter while gripping move the foremost edge of the sheet into engagement with the rotating arbor and the wire being wound thereon. 5
82. A coil winding machine comprising, in combination, a coil winding arbor; a wire guide reciprocable along the arbor; means for reciprocating said wire guide; an electric motor for rotating the arbor; means for intermittently decreasing the speed of the motor as the coil diameter increases; a paper gripping carriage movable laterally with respect to the arbor and adapted to receive and feed a sheet of paper between the rotating arbor and the wire being wound thereon 40 so as to form an insulating layer between adjacent layers of wire; springs urging the carriage toward the arbor; knives for cutting off the ends of the insulating paper wrappings which extend beyond the ends of the layers of wire as the arbor rotates; a mechanism for moving the knives into cutting engagement with the paper wrappings; and means responsive to reciprocation of the wire guide for actuating the motor speed decreasing means and for operating the knife moving mechanism. 45
83. A coil winding machine comprising, in combination, a coil winding arbor; a wire guide reciprocable along the arbor; means for reciprocating the wire guide; an electric motor for operating the machine; a paper gripping carriage movable laterally with respect to the arbor and adapted to receive and feed a sheet of paper between the rotating arbor and the wire being wound thereon so as to form an insulating layer between adjacent layers of wire; springs urging the carriage toward the arbor; a pawl normally latching the carriage in a position most remote from the arbor; means for releasing the pawl from the carriage; knives for cutting off the ends of the insulating 60 paper wrappings which extend beyond the ends of the layers of wire as the arbor rotates; a mechanism for moving the knives into cutting engagement with the paper wrappings; and means responsive to reciprocation of the wire guide for 65
- 70
- 75

operating the pawl releasing means and the knife moving mechanism.

84. A coil winding machine comprising, in combination, a coil winding arbor; a reciprocable wire guide for guiding wire in layers upon the arbor; an electric motor for rotating the arbor; means for intermittently decreasing the speed of the motor as the coil diameter increases; a pair of separable paper gripper bars movable together laterally with respect to the arbor in order to inject a sheet of paper between the rotating arbor and the wire being wound thereon so as to form paper wrappings between adjacent layers of wire; means for moving the bars toward and away from the arbor; means for separating the bars so as to permit the introduction between the bars of a sheet of paper with the foremost edge thereof being in close proximity to the arbor and the wire being wound thereon; means for causing the bars to grip the paper sheet; and means responsive to reciprocation of the wire guide for actuating the motor speed decreasing means and for operating the bar separating means.

85. A coil winding machine comprising, in combination, a rotatable coil winding arbor; a reciprocable wire guide for guiding wire in layers upon the arbor; a pair of separable paper gripper bars movable together laterally with respect to the arbor in order to inject a sheet of paper between the rotating arbor and the wire being wound thereon so as to form paper wrappings between adjacent layers of wire; means for moving the bars toward and away from the arbor; means for separating the bars so as to permit the introduction between the bars of a sheet of paper with the foremost edge thereof being in close proximity to the arbor and the wire being wound thereon; means for causing the bars to grip the paper sheet; knives for cutting off the ends of the paper wrappings which extend beyond the ends of the layers of wire as the arbor rotates; a mechanism for moving the knives into cutting engagement with the paper wrappings; and means responsive to reciprocation of the wire guide for actuating the bar separating means and for operating the knife moving mechanism.

86. A coil winding machine comprising, in combination, a coil winding arbor; a reciprocable wire guide; an electric motor for rotating the arbor; means for intermittently decreasing the speed of the motor as the coil diameter increases; a paper gripping carriage movable laterally with respect to the arbor and adapted to receive and feed a sheet of paper between the rotating arbor and the wire being wound thereon so as to form an insulating layer between adjacent layers of wire; springs urging the carriage toward the arbor; a pawl normally latching the carriage in a position most remote from the arbor; means for releasing the pawl from the carriage; knives for cutting off the ends of the insulating paper wrappings which extend beyond the ends of the layers of wire as the arbor rotates; a mechanism for moving the knives into cutting engagement with the paper wrappings; and means responsive to reciprocation of the wire guide for actuating the motor speed decreasing means, for operating the pawl releasing means and for operating the knife moving mechanism.

87. A coil winding machine comprising, in combination, a coil winding arbor; a reciprocable wire guide for guiding wire in layers upon the arbor; an electric motor for rotating the arbor; means for intermittently decreasing the speed of the motor as the coil diameter increases; a pair

of separable paper gripper bars movable together laterally with respect to the arbor in order to inject a sheet of paper between the rotating arbor and the wire being wound thereon so as to form paper wrappings between adjacent layers of wire; means for moving the bars away from the arbor; yielding means urging the bars toward the arbor; a pawl normally latching the bars in a position most remote from the arbor; means for releasing the pawl from the bars; means for separating the bars so as to permit the introduction between the bars of a sheet of paper with the foremost edge thereof being in close proximity to the arbor and the wire being wound thereon; means for causing the bars to grip the paper sheet; and means responsive to reciprocation of the wire guide for actuating the motor speed decreasing means, for actuating the bar separating means and for operating the pawl releasing means.

88. A coil winding machine comprising, in combination, a rotatable coil winding arbor; a reciprocable wire guide for guiding wire in layers upon the arbor; a pair of separable paper gripper bars movable together laterally with respect to the arbor in order to inject a sheet of paper between the rotating arbor and the wire being wound thereon so as to form paper wrappings between adjacent layers of wire; means for moving the bars away from the arbor; yielding means urging the bars toward the arbor; a pawl normally latching the bars in a position most remote from the arbor; means for releasing the pawl from the bars; means for separating the bars so as to permit the introduction between the bars of a sheet of paper with the foremost edge thereof being in close proximity to the arbor and the wire being wound thereon; means for causing the bars to grip the paper sheet; knives for cutting off the ends of the paper wrappings which extend beyond the ends of the layers of wire as the arbor rotates; a mechanism for moving the knives into cutting engagement with the paper wrappings; and means responsive to reciprocation of the wire guide for actuating the bar separating means, for actuating the pawl releasing means and for operating the knife moving mechanism.

89. A coil winding machine comprising, in combination, a coil winding arbor; a reciprocable wire guide for guiding wire in layers upon the arbor; an electric motor for rotating the arbor; means for intermittently decreasing the speed of the motor as the coil diameter increases; a pair of separable gripper bars movable together laterally with respect to the arbor in order to inject a sheet of paper between the rotating arbor and the wire being wound thereon so as to form paper wrappings between adjacent layers of wire; means for moving the bars toward and away from the arbor; means for separating the bars so as to permit the introduction between the bars of a sheet of paper the foremost edge of which is in close proximity to the arbor and the wire being wound thereon; means for causing the bars to grip the paper sheet; knives for cutting off the ends of the paper wrappings which extend beyond the ends of the layers of wire as the arbor rotates; a mechanism for moving the knives into cutting engagement with the paper wrappings; and means responsive to reciprocation of the wire guide for actuating the motor speed decreasing means, for actuating the bar separating means and for operating the knife moving mechanism.

90. A coil winding machine comprising, in combination, a coil winding arbor; a reciprocable

wire guide for guiding wire in layers upon the arbor; an electric motor for rotating the arbor; means for intermittently decreasing the speed of the motor as the coil diameter increases; a 5 pair of separable paper gripper bars movable together laterally with respect to the arbor in order to inject a sheet of paper between the rotating arbor and the wire being wound thereon so as to form paper wrappings between adjacent 10 layers of wire; means for moving the bars away from the arbor; yielding means urging the bars toward the arbor; a pawl normally latching the bars in a position most remote from the arbor; means for releasing the pawl from the bars; 15 means for separating the bars so as to permit the introduction between the bars of a sheet of paper the foremost edge of which if in close proximity to the arbor and the wire being wound thereon; means for causing the bars to grip the 20 paper sheet; knives for cutting off the ends of the paper wrappings which extend beyond the ends of the layers of wire as the arbor rotates; a mechanism for moving the knives into cut-

ting engagement with the paper wrappings; and means responsive to reciprocation of the wire guide for actuating the motor speed decreasing means for actuating the pawl releasing means, for actuating the bar separating means and for operating the knife moving mechanism. 5

91. The combination of a frame; a rotatable mandrel and means for winding wire thereon; a reciprocating carriage member arranged to reciprocate toward and away from said mandrel; 10 a member mounted on the frame and spaced from said carriage member; a spring roller; an apron having one end wound on said roller, the roller being mounted on one member and the other end of the apron being fixed to the other 15 member.
